LABEL CUTTING AND FOLDING MACHINE

Edward J. Hubelmeyer, Little Ferry, N. J., assignor to Nu Label Machine Corporation of New Jersey, Little Ferry, N. J., a corporation

Application March 9, 1950, Serial No. 148,722

54 Claims. (Cl. 270—61)

1

This invention relates to label cutting and folding machines and particularly to an improved machine for cutting and folding fabric or cloth labels or similar strip material.

Fabric labels, such as those conventionally sewn in garments, are usually manufactured in the form of elongated strips having the label design sequentially woven thereon. In order to prepare individual labels for attachment to garments, it is necessary to sever the individual labels from the label strip symmetrically with respect to the identifying indicia thereon, fold the ends of the severed portion beneath the surface of the label presenting the identifying indicia to provide smooth and uniform edges defining a label of a particular length having the identifying indicia centered thereon, press the folded edge to secure a sharp crease therein, and then stack and pack a suitable number of the folded and pressed labels in a container for shipment. The above series of basic operations has been generally standardized and is required by the trade in order to prepare fabric or cloth labels for further use as identifying indicia in garments and like articles.

The above series of operations are performed, conventionally in the order above presented, by label cutting and folding machines. The dimensions of garment labels, however, vary over relatively wide limits, particularly with respect to length and also with respect to width, and conventional label cutting and folding machines are normally adaptable, in some manner, to accommodate labels of varying dimensions. In many of the label cutting and folding machines now in common use, an excessive amount of time is needed for the adaptation and multiple adjustments required when adapting the machine to accommodate a label of a length differing from that previously operated upon. In some of the commonly used machines, a replacement of certain machine elements is required for each label size, and the installation of these elements and accompanying adjustment of the machine is a time-consuming and relatively difficult procedure. In such machines a set of machine elements corresponding to each label size is required to be kept on hand and available for use. In most of the label cutting and folding machines, now in use, the services of a mechanic or technician are required to adapt and adjust the machine when changing from labels of one dimension to another and in normal operation of label cutting and folding machines, this time required for adapting and adjusting the machine to accommodate

2

a different size label may be an appreciable percentage of the actual available operating time for the machine in question, particularly when relatively small orders are handled. During the change-over period, the operator of the machine, who is usually incapable of performing the change-over operations, is required to sit idly by while the machine is being converted by more highly skilled or technical personnel.

10 The invention may be briefly described as an improved label cutting and folding machine of novel construction and arrangement which may be readily adapted to accommodate labels of varying dimensions by unskilled personnel in a relatively short period of time. The label operating elements of the machine are mounted on a pair of spaced supporting standards, with means whereby the spacing between said standards may be easily varied in accordance with the length of label to be cut and folded. Also included are means whereby the driving linkages for the label strip feeding elements and the label operating elements are automatically varied in accordance with the spacing of the supporting standards. 15 The invention also includes an improved label strip feeding assembly whose driving linkage is adjustably and automatically varied in accordance with the length of label to be cut and folded; improved means for positively and securely clamping the labels during operation, improved means for folding and pressing the labels and improved means for stacking and packing the folded and pressed labels for shipment. Also included are means for trimming the ends of labels so as to center the label indicia with respect to the fold and for providing folds of equal length when operating upon a label strip whose identifying indicia is unsymmetrically disposed thereon.

20 25 30 35 The primary object of this invention is to provide an improved label cutting and folding machine.

Another object of this invention is to provide an improved label cutting and folding machine of novel construction whose major components may be simultaneously and automatically adapted to accommodate labels of varying dimensions by a single control.

Another object of this invention is to provide an improved label strip feeding assembly whose driving linkage may be automatically varied in accordance with the length of label to be cut and folded.

Another object of this invention is to provide an improved means for clamping labels during the

3

operations upon said labels in a label cutting and folding machine.

Another object of this invention is to provide an improved folding and pressing assembly for label cutting and folding machines.

Another object of this invention is to provide an improved stacking mechanism for stacking pressed and folded labels in a label cutting and folding machine.

Another object of this invention is to provide an improved label cutting and folding machine including means for trimming unsymmetric labels so as to center the label indicia with respect to the folded portions thereof and to provide labels having folded portions of equal length.

A further object of this invention is to provide an improved label cutting and folding machine wherein all adjustments necessary to adapt the major components of the machine to varying sizes of labels are automatically and simultaneously varied in accordance with the length of label to be cut and folded.

A further object of this invention is to provide a label cutting and folding machine which is economical and efficient in operation.

Still another object of this invention is to provide an improved label cutting and folding machine that is simple and safe in operation.

Still another object of this invention is to provide an improved label cutting and folding machine of novel construction.

A further object of this invention is to provide an improved label cutting and folding machine which may be easily and quickly adapted to accommodate labels of varying dimensions by unskilled personnel.

A still further object of this invention is to provide an improved label cutting and folding machine wherein the wastage of labels accompanying the adaptation of the machine to labels of varying dimensions is greatly reduced.

Other objects and advantages of this invention will be apparent in the following specification and accompanying drawings.

The presently preferred embodiment of the invention, as illustrated in the drawings, may generally be described as an improved label cutting and folding machine whose major label operating components may simultaneously be adapted to accommodate labels of varying lengths by a single control in accordance with the length of label to be cut and folded. For the purposes of simplicity and for clarity of explanation, a general description of the major components of the machine, together with their function and general mode of operation, will be initially described and will be followed by a detailed description of the structure, mode of operation, and interrelation of operations of the individual components.

Integrally combined in the presently preferred embodiment of the invention are: (1) a main drive system, including a horizontal rotatable drive shaft fixed in position and having three drive cams fixedly mounted thereon in spaced relationship with each other and adapted to rotate in conjunction with the main drive shaft.

Included in the main drive system are a plurality of fixed supporting elements for the main drive shaft. During operation of the machine, the power for all the mechanical movements of the label operating components is obtained by suitable individual mechanical linkages from the

75

above mentioned three fixed drive cams. The drive system and its mountings remain fixed in location, other than for movements related to rotation of said main drive shaft, irrespective of the length of label to be cut and folded, and irrespective of the positioning of the label operating elements with respect thereto. (2) A pair of substantially parallel, upright supporting members, or standards, upon which all of the machine components relating to the operations to be performed upon the labels, are mounted or supported. These supporting standards are perpendicularly disposed with respect to the main drive shaft described above and are provided with suitable apertures therein to permit the passage of said main drive shaft therethrough. The standards are positioned so that the intermediate drive cam of the above mentioned three drive cams is positioned between said standards with the remaining two drive cams being symmetrically positioned externally of the space between said standards. A slidable mounting is provided for the main supporting standards whereby the spacing between said standards may be varied in accordance with the length of label to be cut and folded. The standards move with respect to the fixed drive cams. As it may be generally stated that corresponding operations are required to be performed on each end of the label or labels, corresponding label operating elements which function in a similar manner are symmetrically mounted on each of said supporting standards. (3) A label strip advancing assembly for horizontally advancing a portion of a label strip across the space between the above mentioned supporting standards. The label strip advancing assembly includes a first reciprocating label strip advancing carriage mounted on one of the supporting standards for advancing the end of a label strip to the approximate center of the space between said standards. Coacting with said first reciprocating label strip advancing carriage is a second reciprocating label strip advancing carriage, supported on the other of said supporting standards and having mounted thereon a pair of label strip gripping jaws adapted to grasp the end of the label strip after it has been advanced to the approximate center of the space between said standards by the first mentioned label strip advancing carriage and to advance the strip across the remaining distance of the space between the supporting standards. The amplitude of reciprocation of these reciprocating carriages must be varied in accordance with the spacing between said standards. Each of said carriages is driven through a separate mechanical drive linkage by the fixed drive cams positioned externally of the space between the supporting members. The drive linkages each include means by which the amplitude of reciprocation of said carriages is automatically varied in accordance with the spacing of said standards. The label strip gripping jaws mounted on the second label strip advancing carriage are actuated in the proper cyclic relationship independent of the spacing of the supporting standard through a separate mechanical drive linkage by one of said fixed drive cams. This drive linkage includes means by which the label strip gripping jaws are opened and closed in the proper cyclic relationship independent of the spacing of the supporting standards. (4) An independent, vertically reciprocating clamping assembly mounted on each of the supporting standards and adapted to clamp the advanced portion of the label strip adjacent the supporting

members during the cutting operations and adapted to transfer the severed portion of the label to the folding and pressing assembly. As a clamping assembly is mounted on each of the supporting standards, the distance between the clamping assemblies varies in accordance with the spacing of the standards. The clamping assemblies are driven by the intermediate driving cam positioned in the space between said supporting standards through a separate mechanical linkage which includes means by which said assemblies may be operated in the proper cyclic relationship independent of the spacing of the supporting members. (5) A cutting assembly by which the advanced portion of the label strip is severed from the remainder of the label strip. The cutting mechanism includes a pivoted knife member mounted on one of the supporting standards and driven by one of the fixed drive cams through a separate mechanical drive linkage which includes means by which the knife member may be operated in the proper cyclic relationship independent of the spacing of the supporting standards. (6) Associated with the cutting mechanism and the first label strip advancing carriage are means by which the leading and trailing edges of unsymmetric labels may be automatically trimmed prior to the introduction of the severed label into the label operating components. When required, the trimming operation results in a finished label whose identifying indicia is centered with respect to the folded portion thereof and whose folded portions are of substantially equal length. (7) A label folding and pressing assembly, including a folding and pressing unit mounted on each of the supporting standards for folding and pressing the severed portion of the label strip in cooperation with a portion of the clamping assembly set forth briefly above. The label folding and pressing units are driven by the intermediate drive cam positioned between the supporting standards through suitable mechanical linkages which include means by which said assembly may be operated in the proper cyclical relationship independent of the spacing of the supporting members. (8) A label stacking assembly, including a stacking unit supported by each of said supporting standards for transferring the folded and pressed label from the folding and pressing assembly into a container for shipment. The stacking assembly is provided with a mechanical drive linkage for proper cyclic operation independent of the spacing of the supporting standards. (9) A packing assembly including a packing unit associated with each of the supporting standards for compressively packing the folded and pressed labels in a container for shipment. These packing units are also provided with a mechanical drive linkage affording proper cyclic operation independent of the spacing of the supporting standards.

In operation, the main supporting standards are spaced in accordance with the length of label to be cut and folded. This is the only major adjustment required to prepare the machine for operation as each of the label strip feeding or label operating components is provided with a mechanical drive linkage which is automatically varied in accordance with, or operates independently of the spacing of the supporting standards. After the spacing of the main supporting standards has been set in accordance with the length of label to be cut and folded and a label strip is inserted in operative relationship with the label

strip feeding system, the first reciprocating label strip advancing carriage advances the end of the label strip to the approximate center of the space between the supporting standards in a line across the top of and perpendicular to the plane of the standards. The end of the label strip is then grasped by the label strip gripping jaws mounted on the second label strip advancing carriage and advanced across the remainder of the distance of the space between the standards. After the label strip has been advanced, the advanced portion is securely clamped adjacent the supporting standards by the clamping assembly. The advanced clamped portion of the label strip is then severed from the remainder of the label strip by the cutting mechanism. The severed clamped portion of the label strip, which is the label to be operated upon, is then moved into the folding and pressing assembly where the end portions thereof are folded with the cooperation of a portion of the clamping assembly. The folding and pressing assembly, together with the folded label is then moved out of engagement with the clamping assembly. After the folding and pressing assembly has cleared the clamping assembly, the folded portions of the label are pressed to provide a sharply creased folded edge. The stacking assembly removes the folded and pressed label from the folding and pressing assembly and transfers it into a container for shipment. The packing assembly maintains the stacked labels in an orderly compact array in the container.

The above operations are performed for labels of any length and it should be kept in mind that each of the label operating or label strip feeding components is operated by the fixed drive cams through a mechanical drive linkage in the proper cyclic operation irrespective of the spacing of the supporting standards.

The structures of the above enumerated components of the invention, together with their modes of operation and interrelationship with each other, will now be examined and described in detail.

(1) *Main drive system*

Referring to Figs. 1-10 and particularly to Figs. 1, 2, 4, 5 and 8, the presently preferred embodiment of the label cutting and folding machine is mounted on a roughly rectangular base plate 10 which is supported by and rests upon an operating table or platform 12. The operating platform 12 is provided with a conveniently located aperture 14 through which a drive belt 16 may pass. Positioned beneath the operating platform 12 is a suitable drive unit, not shown, which may be an electric motor or other prime mover for supplying the power for operating the machine through a drive pulley 18 (see Fig. 10).

Perpendicularly mounted at each end of the base plate 10 are the fixed main drive system supporting members 20 and 22. Included in the main drive system supporting assembly is an auxiliary fixed supporting member 24 supported by and spaced from the main supporting member 20 and by the supporting shafts 26, 28 and 30. Rotatably supported by the main drive system supporting member 20 and the auxiliary supporting member 24 is a power transmission shaft 32 (see Fig. 4). Mounted on the portion of the shaft 32 disposed between the supporting members 20 and 24 is a multiple channel drive pulley 34 drivingly engaged by the drive belt 16. A gear 36 is mounted on said shaft 32 on the portion thereof extending beyond the main drive system sup-

porting member 20. Rotatably supported by the main drive system supporting members 20 and 22 is the main drive shaft 38. Mounted on the main drive shaft 38 and meshing with and driven by the gear 36 is a pinion 40. Thus, rotation of the multiple channel drive pulley 34, in response to the action of the drive belt 16, results in rotation of the main drive shaft 38 through the mechanical linkage of the gear 36 and the pinion 40.

Mounted on the main drive shaft 38 adjacent the pinion 40 is a drive cam 42 (see Figs. 1, 4 and 8). The drive cam 42 is fixed in position on the main drive shaft 38 and rotates in conjunction therewith. Also mounted on the main drive shaft 38 a predetermined distance from, and in spaced relationship with the cam 42, is an intermediate drive cam 44 and a third drive cam 46. The drive cams 44 and 46 are fixed in position on said main drive shaft 38 and rotate in conjunction therewith.

The drive cams 42, 44 and 46 are provided with internal cam tracks on each side of each cam in addition to having an external cam track on the surface. Thus each of the cams 42, 44 and 46 may be utilized to provide three cyclically operated drives depending on the shapes of the respective cam tracks.

The main drive shaft supporting members 20 and 22 also serve as a fixed mounting for the cam follower lever arm supporting shafts 48 and 50, each of said shafts being utilized to provide a pivotal support for the cam follower lever arms associated with each of the three drive cams 42, 44 and 46.

To provide for manual rotation of the main drive shaft 38 a relatively heavy hand wheel 52 is mounted on a reduced portion 54 of the main drive shaft 38 extending beyond the main drive system supporting member 22. The handwheel 52 also functions as a fly wheel to provide smooth operation.

The above described main drive system is fixed in location with respect to the base 10, other than positional changes due to rotation of the main drive shaft 38 and members associated therewith, irrespective of the length of label to be cut and folded.

(2) *Supporting standards*

Referring to Figs. 1-10 and particularly to Figs. 1, 2, 4, 5 and 8, the label operating components of the machine are mounted on a pair of upright substantially parallel supporting members or standards 60 and 62. Each of the standards 60 and 62 is supported at the front of the machine and spaced from the base 10 thereof (see Figs. 1, 2 and 8) by a single slidable support block, such as the adjacent blocks 64 and 66 which rest in sliding relationship upon the surface of the base plate 10. To channel the support blocks 64 and 66 and to direct their sliding movement on the surface of the base plate 10, suitable fixed guiding members or channel blocks 68, 70 and 72 are provided. Each of the standards 60 and 62 is supported at the rear of the machine (see Figs. 4 and 5) by similar slidable support blocks 74 and 76 guided in their sliding movement on the surface of the base plate 10 by suitable fixed guiding members or channel blocks 78, 80 and 82. As the main supporting standard 60 is secured to the slidable support blocks 64 and 76, and as the main supporting standard 62 is secured to the slidable support blocks 66 and 74, each of the standards may be moved with respect to the fixed base plate 10

75

and the fixed main drive assembly described above. Suitable apertures are provided in the main supporting standards 60 and 62 to permit movement of these standards relative to the main drive assembly and to permit the movement of said standards relative to the fixed cam follower lever arm supporting shafts 48 and 50. The space between the main supporting standards 60 and 62 and identified at 84 on Fig. 1 may be designated as the label operating zone. The main supporting standard 60 is positioned between the intermediate drive cam 44 and the drive cam 42. The main supporting standard 62 is positioned between the intermediate drive cam 44 and the drive cam 46.

Mounted on the lower portions of each of the main supporting standards 60 and 62 and positioned beneath the main drive shaft 38 are the plates 86 and 88, respectively. The plates 86 and 88 extend the length of the supporting members 60 and 62 and are offset from said supporting standards 60 and 62 by the spacing members 90 and 92 at the front of the machine (see Figs. 1 and 2) and the spacing members 94 and 96 at the rear of the machine (see Figs. 4 and 5).

To vary the spacing between the supporting members or standards 60 and 62 and to vary the extent of the label operating zone 84 located therebetween, there is provided a spacer shaft 98 having a knob or wheel 100 provided for manual manipulation thereof (see Figs. 1, 2, 4 and 8). The spacer shaft 98 is provided with oppositely threaded portions 101 and 103 which are in threaded engagement with the internally threaded collars 102 and 104 mounted on the plates 86 and 88, respectively.

The spacer shaft 98 is rotatably supported by the main drive system supporting member 28 and the threaded portions 101, 103 thereon are threadedly engaged with the threaded collars 102 and 104 in such a manner that when the spacer shaft 98 is rotated in one direction, the main supporting members 60 and 62 move towards each other, thus decreasing the extent of the operating zone 84, and when the spacer shaft 98 is rotated in the opposite direction, the main supporting members 60 and 62 move apart to increase the extent of the operating zone 84. The extent of the operating zone 84 may be visually and accurately determined by a scale, such as 106, (see Figs. 1, 2, 4 and 7), fixed to one of the supporting standards and maintained in sliding relationship with the other. The standards 60 and 62 are maintained substantially parallel at all times by the channel blocks 68, 70, 72 and 78, 80, 82 described above.

In operation of the machine, the operator once having accurately ascertained the length of label to be cut and folded, manipulates the knob 100 and sets the spacing of the standards 60 and 62 in accordance with the length of label as indicated by the scale 106. This is the only major adjustment required when changing from labels of one folded dimension to another.

(3) Label strip advancing assembly

Labels are normally supplied to the label cutting and folding machine in the form of a roll of labels having the identifying indicia sequentially woven thereon. To accommodate and support a roll of labels, a label roll supporting assembly including a pair of upright members 112 and 114 having axle-receiving slots 116 and 118 vertically disposed therein are provided (see Figs. 1, 2, 4, 5, 6, 7, 8 and 10). The upright members

112 and 114 each terminate in a dove-tailed section 120 which are secured in a correspondingly shaped bracket 122. To accommodate rolls of labels of different widths, the upright members 5 112 and 114 are slidably contained within the dove-tailed mounting bracket 122 and suitable locking screws 124 are provided to secure said members after they have been spaced to accommodate the width of label roll required. The label roll supporting assembly is spaced a suitable distance from the main body of the machine by the extended arm 126 secured to the main drive assembly supporting member 28.

Positioned above the label roll supporting assembly and adjacent thereto is a label strip tensioning roll 128 rotatably supported by the tensioning roll supporting bracket 130. Mounted on the tensioning roll 128 are a plurality of tensioning fingers 132 adapted to have the label strip threaded therethrough in a predetermined manner. A proper degree of tension to retard the advance of the label strip, to assure a flat positioning thereof during feeding operations, and to aid in the uniform feeding thereof, is obtained 20 by the weight 134 suspended by the cord 136 from the tensioning roll pulley 138.

In operation, a roll of labels having a suitable axle or shaft is inserted into the label roll supporting assembly with the axle or shaft contained within the axle-receiving slots 116 and 118. The end of the roll of labels is then threaded through the tensioning fingers 132 on the tensioning roll 128 and advanced upwardly toward the portion of the label strip advancing assembly 30 provided to advance the end of the label strip to and 35 the approximate center of the operating zone 84. This portion of the label strip advancing assembly is designated generally as A on Figs. 1, 2, 4, 5, 6, 7 and 8.

Included in the portion of the label strip advancing assembly provided to advance the end of the label strip to the approximate center of the operating zone 84 is a fixed horizontal supporting platform 144 secured to and having its horizontal surface mounted in line with the upper portion of the main supporting standard 60. The platform 144 is supported at its unsecured end by the supporting shaft 145 connected to the auxiliary main drive system supporting member 24. Mounted on the platform 144 and in movable relationship therewith is a first label strip advancing carriage 146. The mounting of the carriage 146 on the platform 144 is similar in construction to the mounting of the second label strip advancing carriage having the label strip gripping jaws mounted thereon which will be described in detail at a later point in this section of the specification. However, it may generally be stated at this point that a suitable fixed track member is included in the platform 144 which is engaged by flanged rollers mounted on the underside of the movable label strip advancing carriage 146. This construction permits movement of the carriage 146 relative to the fixed platform 144 in a direction limited by the position of the track, which is positioned horizontally and perpendicularly to the plane of the main supporting standard 60.

Referring now particularly to Figs. 1, 2, 4, 5, 6 and 7, the label strip advancing carriage 146 is provided with a plane upper surface having a slidable label strip guiding member 148 and a fixed label strip guiding member 150 mounted thereon, to accommodate the feeding of labels of varying widths. The slidable label strip guiding member 148 is secured to the carriage 146 and

11

guided in its sliding movement by the pins 152 riding in the channels 154 in the surface of said carriage 146. Suitable spring members, not shown, may be mounted beneath the channels 154 in operative relationship with the pins 152 to maintain the guiding member 148 in compressive slidable engagement with the surface of the label strip advancing carriage 146. The guiding members 148 and 150 are provided with undercut edge portions 156 along their lengths (see Figs. 5 and 7), adapted to encompass the edges of the advancing label strip. The undercut edge portions 156 of the guiding members 148 and 150 serve to maintain the portion of a label strip disposed in feeding relationship on the surface of the label strip advancing carriage 146 in feeding alignment and to aid in the maintenance of the strip in a flat condition during feeding operations.

To facilitate the feeding of label strips into conventional label cutting and folding machines, the strip is generally increased in thickness, as by introducing extra picks in the weave, or introducing heavier material in the filling, on the line of demarcation between successive labels on the strip. The increase in thickness provides a convenient raised abutment which is utilized as a feeding index in the feeding operations. These abutments are not necessary for operation of the machine as a portion of the identifying indicia woven therein may be used with no loss in efficiency. For the purpose of convenience, the operation will be explained in conjunction with a raised feeding abutment of the type described above. To move the label strip in conjunction with the feeding movement of the label strip advancing carriage 146, a label strip advancing stop or feed finger 158, adapted to engage the raised portions intermediate the individual labels on the label strip, is provided. The feed finger 158 is mounted on a rotatable horizontal supporting arm 160 and is maintained in feeding relationship with the surface of the carriage 146 by the spring 162 connected between a fixed arm 164 and a lever arm 166 connected to said rotatable supporting arm 160. The rotatable supporting arm 160 is mounted on a member 161 slidably contained within a track 167 contained within the feed finger supporting bracket 168 (see Fig. 4) which is maintained in spaced relationship with the surface of the carriage 146 and supported by the spacing members 170 and 172. A suitable locking thumbscrew 169 is provided to securely position the member 16 within the track 167 after the feed finger 158 has been longitudinally located with respect to the carriage 146, i. e., against the raised abutment of the label strip disposed on the surface of said carriage 146. To permit the handling and feeding of label strips having intermediate abutments or identifying indicia of varying heights, the spacing between the surface of the carriage 146 and the operating edge of the feed finger 158 may be varied by the spacing screw 174 mounted on the extension arm 176 secured to said feed finger 158 (see Figs. 1, 2, 4, 5 and 7). However, as the heights of the feeding abutments are fairly uniform, the setting of the spacing screw 174 will normally remain unchanged during operations on different rolls of labels. Fine adjustment of the longitudinal location of the feed finger 158 with respect to the carriage 146 may be obtained by moving the entire supporting bracket 168 with respect to the carriage 146. A thumb screw 178 rotatably secured to the carriage 146 and thread-

edly engaged with the spacing member 172 is provided for such fine adjustments.

During feeding operations the end of a roll of labels supported in the label roll supporting assembly is threaded through the tensioning roll 126 and placed in feeding engagement with the indicia-presenting surface face down on the plane upper surface of the carriage 146 with the feed finger 158 in engagement with the raised feeding abutment on the line of demarcation between successive labels on the strip. As the carriage 146 moves toward the operating zone 84, the label strip is advanced therewith due to the pushing action of the feed finger 158 on the feeding abutment. On the return cycle of the carriage 146, i. e., its movement away from the center of the operating zone 84, the label strip is maintained in movement across the operating zone 84 (by means to be described at a later point in this section of the specification) and the movement of the carriage 146 is relative to the continually advancing label strip. The feeding edge of the feed finger 158 is suitably beveled so as not to engage the next successive feeding abutment on the label strip in feeding relationship during the return portion of the cycle of the carriage 146.

The label strip advancing carriage 146 is, during feeding operations, adapted to reciprocate in a path perpendicular to the plane of the main supporting standard 60. The path of reciprocation of the carriage 146 is determined by its mounting on the horizontal supporting platform 144. The details of a similar carriage mounting will be described at a later point in this section of the specification.

As the label strip advancing carriage 146 is supported by the horizontal label strip advancing carriage supporting platform 144, which is securely mounted on the upper portion of the slideable main supporting standard 60, and as the carriage 146 must advance the end of the label strip to the approximate center of the operating zone 84 during feeding operations, the amplitude of reciprocation of said carriage 146 must vary in accordance with the spacing of said standard 60 from the center of the operating zone 84. As mentioned at an earlier point in this specification, the spacing of the supporting standards 60 and 62 is set in accordance with the length of label to be cut and folded. To automatically vary the amplitude of reciprocation of the carriage 146 in accordance with the length of label to be cut and folded, automatic means, to be described in the following portions of this section of the specification, are included in the mechanical driving linkage for the carriage 146.

The drive for the label strip advancing carriage 146 is best illustrated in Figs. 1, 2, 4, 5 and 8, and a detailed oblique skeletonized view of the essentials of the drive linkage is shown in Fig. 13. The drive for the reciprocating label strip advancing carriage 146 originates at the fixed drive cam 42 mounted on the main drive shaft 38 adjacent the main drive shaft pinion 40 described at an earlier point in this specification. The drive cam 42 is provided with a suitably shaped cam track 184 on the side of the cam facing the main supporting standard 60. Contained within the cam track 184 is a rotatable cam follower 186 mounted on one arm of a bifurcated cam follower lever arm 188 (see Figs. 1, 2, 4, 8 and 13). The cam follower lever arm 188 is pivotally mounted at one end on the fixed cam follower lever arm supporting shaft 43. The cam follower lever arm 188 has a ball joint mounting 190 at its movable end on which is mounted a connecting rod 192

(see Figs. 1, 2, 8 and 13). The connecting rod 192 is secured at its other end in a similar ball joint mounting 193 to the free end of a slotted lever arm 196. The lever arm 196 is pivotally mounted at its other end to a bifurcated mounting lug 198 mounted on a member 199 secured to a fixed housing of the intermediate drive cam 44. The bifurcated mounting lug 198 is fixed in position and does not move irrespective of the spacing of the standard 60, a suitable aperture being provided in the standard 60 to permit relative movement between said standard 60 and the fixed lug 198. All of the above described members, i. e., the drive cam 42, the cam follower lever arm 188, the cam follower lever arm supporting shaft 48, the connecting rod 192 and the slotted lever arm 196 remain fixed in position with respect to the main drive system except for movements related to rotation of said drive cam 42, irrespective of the location of the supporting standard 60.

Rotation of the drive cam 42 results in a pivoting of the cam follower lever arm 188 about the cam follower lever arm supporting shaft 48 and the arc through which the free end moves is determined, for a lever arm of a given length, by the shape of the cam track 184. The ball joint mountings 190 and 194 enable the connecting rod 192 to transmit the arcuate motion of the free end of the cam follower lever arm 188 in one plane into arcuate motion of the free end of the slotted lever arm 196 in a plane perpendicular thereto. Thus, in response to rotation of the drive cam 42, the slotted lever arm 196 is pivotally moved about the bifurcated mounting lug 198.

The slotted lever arm 196 is provided with a slot 200 along the major portion of its length. Riding within the slot 200 is a roller 202 rotatably secured to one end of a substantially vertically disposed connecting rod 204. The other end of the connecting rod 204 is pivotally secured to one arm 201 of a bell crank 203. The bell crank 203 is pivotally mounted on the bell crank supporting stanchion 210 suspended from the horizontal label strip advancing carriage supporting platform 144 mounted on the main supporting standard 60 and further fixed in position by the horizontally disposed supporting member 211 secured at one end to said standard 60.

To permit movement of the carriage 146 independent of the above described drive linkage during trimming operations, there is mounted adjacent the bell crank 203 and rotatable about the same shaft on the bell crank supporting stanchion 210, a second bell crank 208 having a bifurcated arm 206. The bell crank 208 is mounted so as to permit movement thereof independent of the bell crank 203 as well as in response to movement of the crank 203. The arm 201 of the bell crank 203 is disposed adjacent to and overlying the bifurcated portion of the bifurcated arm 206 of the crank 208. The spacing between the bifurcated arm 206 of the crank 208 is of sufficient width to permit the bifurcated arm 206 to move relative to the arm 201 and the connection thereon with the connecting rod 204, through a distance limited by the spacing on either side of the joint between the connecting rod 204 and the arm 201 and the adjacent surfaces of the bifurcated arm 206. The other arm 212 of the bell crank 208 terminates in a sector 214 which engages a rack 216 suspended from and mounted on the underside of the label strip advancing carriage 146. To provide for movement of the bell crank 208 in response to movement of the con-

necting rod 204, the arm 205 of the bell crank 203 is spaced from and drivingly engaged with the arm 212 of the bell crank 208 by an adjustable thumbscrew 207.

If the connecting rod 204 is moved downwardly, the bell crank 203 is rotated about its mounting on the main supporting stanchion 210. The movement of the bell crank 203 moves the bell crank 208 by action of the thumbscrew 207 mounted on the arm 205 of the bell crank 203 and drivingly engaged with the arm 212 of the bell crank 208. Thus, depression of the connecting rod 204 results in rotation of the bell crank 208 about its mounting on the supporting stanchion 210. To maintain the arm 212 of the bell crank 208 in driving engagement with the screw 207 mounted on the arm 205 of the bell crank 203, a tensioning spring 209 connected between the arms 205 and 212 is provided.

The above construction is included to permit a desired relative movement of the bell crank 208 independent of the bell crank 203 during trimming operations as well as a desired dependent movement of the bell crank 203 in response to movement of the crank 203 during the label strip feeding operation. From the above construction, it will be clear that in response to depression of the connecting rod 204, the bell crank 208 will be rotated about its mounting and the engagement of the rack 216 by the sector 214 results in movement of the first label strip advancing carriage 146.

As mentioned at an earlier point in this specification, the invention includes means by which unsymmetric labels may be automatically trimmed prior to introduction of the severed label into the label operating component for folding and pressing of the ends thereof. This construction and operation of these means will be described in detail at a later point in the specification, to wit, section 6 relating to the label trimming assembly. However, the above mentioned means by which unsymmetric labels may be automatically trimmed necessitates a movement of the label strip advancing carriage 146 independent of its normal movement in response to the above described drive linkage. Consequently, the above described construction is such that the bell crank 203 will always be rotated in response to movement of the connecting rod 204 during normal label strip feeding operations. However, the above described construction is one that does permit the crank 208 to be rotated through a small arc, against the action of the spring 209, independent of movement of the bell crank 203. If the bell crank 208 is rotated independently of the bell crank 203, the first label strip advancing carriage would be moved in response thereto.

To rigidly position the roller 202 and the connecting rod 204 with respect to the slotted lever arm 196, a positioning member 218 pivotally secured at one end to the bell crank supporting stanchion 210 and pivotally secured at the other end to the connecting rod 204 is provided.

The arcuate movement of the slotted lever arm 196 resulting from rotation of the drive cam 42, as described above, results in vertical reciprocation of the connecting rod 204 which in turn results in a pivoting of the bell crank 208 through the driving engagement of said crank by the thumbscrew 207 mounted on the bell crank 203. The pivoting of the bell crank 208, through the engagement of the rack 216 by the sector 214,

results in horizontal reciprocating movement of the label strip advancing carriage 146. The amplitude of the arcuate movement of the free end of the slotted lever arm 196 is determined by the configuration of the cam track 84 and the dimensions of the cam follower lever arm 188, and remains constant irrespective of the length of label being operated upon and irrespective of the position of the main supporting standard 60. As the bell crank supporting stanchion 210 is suspended from the horizontal label strip advancing carriage supporting platform 144, the bell cranks 203 and 208 and the connecting rod 204 move relative to the slotted lever arm 196 together with the standard 60 whenever the main supporting standard 60 is shifted in position. The location of the roller 202 with respect to the pivot for the slotted lever arm 196 determines the amplitude of vertical reciprocation of the connecting rod 204 which determines the amplitude of horizontal reciprocation of the label strip advancing carriage 146. If the roller 202 is in the vicinity of the free end of the slotted arm 196, i. e., when the standard 60 is spaced relatively far from the center of the operating zone 84 (to accommodate a relatively long label), the amplitude of vertical reciprocation of the connecting rod 204 will be large, with an accompanying large amplitude of reciprocation for the reciprocating label strip advancing carriage 146; and conversely, when the roller 202 is located in the vicinity of the pivoted end of the slotted arm 196, i. e., when the supporting standard 60 is spaced relatively closely to the center of the operating zone 84 (to accommodate a short label), the amplitude of vertical reciprocation of the connecting rod 204 will be small, with an accompanying small amplitude of horizontal reciprocation for the reciprocating label strip advancing carriage 146.

To aid in obtaining smooth and uniform movement of the label strip advancing carriage 146 in its reciprocating action, the bell crank 208 works against a spring 220 secured in tension between the crank 208 and a spring supporting member 222 mounted on the bell crank supporting stanchion 210.

Through the above described driving linkage, the amplitude of reciprocation of the label strip advancing carriage 146 is automatically varied in accordance with the spacing of the main supporting standard 60, or, stating it in another manner, is automatically varied in accordance with the length of label to be cut and folded.

The label strip advancing carriage 146 is shown in its retracted position in Figs. 1, 2, 4 and 5 and illustrated in a partially advanced position in Fig. 8. Its location in the retracted position, relative to the horizontal label strip advancing carriage supporting platform 144 remains the same irrespective of the spacing of the standard 60 from the center of the operating zone 84. However, the length of stroke of the label strip advancing carriage 146 towards the center of the operating zone 84 varies in accordance with the spacing of the standard 60 from the center of said operating zone 84.

The above described portion of the label strip advancing assembly including the label strip advancing carriage 146 and the components associated therewith, advances the end of a label strip to the approximate center of the operating zone 84 for each rotative cycle of the drive cam 42. Operatively associated with said above described portion of the label strip advancing assembly is an associated portion of said assembly adapted

to advance the end of the label strip from the approximate center of the operating zone 84 across the remaining extent of said zone 84 and is designated generally as B on Figs. 1, 2, 4, 5, 6, 7 and 8.

Included in the portion of the label strip advancing assembly provided to advance the end of the label strip from the approximate center of the operating zone 84 across the remaining extent of said zone, is a fixed horizontal supporting platform 230 secured to and having its upper horizontal surface mounted in line with the upper portion of the main supporting standard 62. The platform 230 is supported at its unsecured end by the supporting shaft 231 mounted on the main drive system supporting member 22. Forming a part of the fixed horizontal supporting platform 230 is a horizontally disposed track 232 (see Figs. 1, 2, 3, 8 and 9) which is engaged by and supports the dual flanged rollers 234 mounted on the underside of the movable second label strip advancing carriage 236. The carriage 236 is adapted to move with respect to the fixed horizontal track 232 and the fixed horizontal platform 230 in a direction determined by the positional location of the track 232 which is disposed perpendicular to the plane of the main supporting standard 62.

Referring now particularly to Figs. 1, 2, 3, 5, 7, 8 and 9, the label strip advancing carriage 236 is provided with a plane upper surface having a pivoted label strip gripping jaw member 238 and a fixed label strip gripping jaw member 240 mounted thereon. The label strip gripping jaw members 238 and 240 are supported and positioned by the label strip gripping jaw positioning and supporting members 242 and 244 mounted on the carriage 236 and the movable jaw member 238 is pivoted in the vicinity of its mid-length. The gripping ends of the jaw members are normally maintained in closed gripping engagement by the action of the springs 246 positioned against the surface of the pivoted gripping jaw member 238 between the gripping ends of said jaw and gripping jaw pivot line. The gripping ends of the jaw members 238 and 240 are opened against the action of the springs 246 by the depressing action of the gripping jaw control lever arm 248 on a suitable stud 250 positioned on the surface of the pivotable jaw member 238. The gripping jaw control lever arm 248 is pivoted about the lever arm supporting bracket 252 mounted on the surface of the carriage 236 and is actuated in the proper cyclic relationship by a linkage, to be described at a later point in this section of the specification, and is guided in its pivotal movement by the slotted guiding member 254.

The second label strip advancing carriage 236 supporting the label strip gripping jaw members 238, 240 is, during feeding operations, adapted to reciprocate in a horizontal path perpendicular to the plane of the main supporting standard 62. The path of reciprocation of the carriage 236 is determined by its mounting on the track 232 which forms a part of the horizontal supporting platform 230. As explained at an earlier point in the specification, the first label strip advancing carriage 146 was adapted to advance the end of the label strip to the approximate center of the operating zone 84. The jaw members 238, 240 mounted on the second label strip advancing carriage 236 are adapted to grasp, in gripping engagement, the end of the label strip which has been advanced to the approximate

center of the operating zone 84 and to draw said label strip across the remaining extent of said operating zone 84 on the return portion of its cycle, i. e., on its cycle of movement away from the center of the operating zone 84. Consequently, the first label strip advancing carriage 146 and the second label strip advancing carriage 236 are adapted to reciprocate together, i. e., they will both move toward the center of the operating zone 84 at the same time and at the same rate and they will both move in a direction away from the operating zone 84 at the same time and at the same rate. During the return cycle of the first label strip advancing carriage 146, i. e., away from the center of the operating zone 84, the first label strip advancing carriage 146 moves in a direction opposite to that of the advancing label strip. During the return stroke of the carriage 236, i. e., away from the center of the operating zone 84, the gripping jaws 238, 240 are maintained in gripping engagement with the end of the label strip and draw said strip across the remaining extent of said operating zone 84. As the carriage 236 is supported by the horizontal supporting platform 230 which is securely mounted on the slideable main supporting standard 62, and as the jaw members 238 and 240 must grasp the end of the label strip in the approximate center of the operating zone 84 during feeding operations, the amplitude of reciprocation of said carriage 236 must vary in accordance with the spacing of said standard 62 from the center of the operating zone 84. As mentioned at an earlier point in the specification, the spacing of the supporting standards 60, 62 is set in accordance with the length of label to be cut and folded. To automatically vary the amplitude of reciprocation of the carriage 236 in accordance with the length of label to be cut and folded, automatic means are included in the mechanical drive linkage for the reciprocating carriage 236.

The drive for the label strip advancing carriage 236 is best illustrated in Figs. 1, 2, 4 and 8 and a detailed oblique view of the essentials of the drive linkage is shown on Fig. 11. The drive for the reciprocating carriage 236 originates at the fixed drive cam 46 mounted on the main drive shaft 38 and positioned intermediate the main supporting standard 62 and the main drive supporting member 22. The drive cam 46 is provided with a suitably shaped cam track 262 on the side of the cam. Contained within the cam track 262 is a rotatable cam follower 264 secured to one arm of a bifurcated cam follower lever arm 266. The cam follower lever arm 266 is pivotally mounted at one end on the fixed cam follower lever arm supporting shaft 48 (see Fig. 4). The cam follower lever arm 266 has a ball joint mounting 268 at its movable end on which a connecting rod 270 (see Figs. 1, 2 and 8) is mounted. The connecting rod 270 is secured at its other end in a similar ball joint mounting 272 to the free end of a slotted lever arm 274. The lever arm 274 is pivotally mounted at its other end to a bifurcated mounting lug 276 mounted on a member 278 secured to a fixed housing of the intermediate drive cam 44. The main supporting standard 62 is provided with a suitable cut-out portion in the vicinity of the mounting lug 276 and the lever arm 274 to permit relative movement between said main supporting standard 62 and said members when varying the extent of the operating zone 84 to accommodate labels of varying lengths. The

bifurcated mounting lug 276 is fixed in position and does not move irrespective of the spacing of the main supporting standard 62. All of the above described members, i. e., the drive cam 46, the cam follower lever arm 266, the cam follower lever arm supporting shaft 48, the connecting rod 270 and the slotted lever arm 274 remain fixed in relative location with respect to the base 10, other than positional changes resulting from rotation of the drive cam 46, irrespective of the location of the main supporting standard 62.

Rotation of the drive cam 46 in response to rotation of the main drive shaft 38 results in a pivoting of the cam follower lever arm 266 about the cam follower lever arm supporting shaft 48 and the arc through which the free end moves is determined by the shape of the cam track 262 for a lever arm 266 of a given length. The ball joint mountings 268 and 272 enable the connecting rod 270 to transmit the arcuate motion of the free end of the cam follower lever arm 266 in one plane into arcuate motion of the free end of the slotted lever arm 274, i. e., resulting from the pivoted movement about the bifurcated mounting lug 276, in a plane perpendicular to the plane of motion of the free end of the cam follower lever arm 274. Thus, in response to rotation of the main drive cam 46, the slotted lever arm 274 is pivoted about the bifurcated mounting lug 276 and the amplitude of the arcuate movement of the end thereof is determined by the configuration of the cam track 262 in the drive cam 46.

The slotted lever arm 274 is provided with a slot 280 along the major portion of its length. Riding within the slot 280 is a roller 282 secured to one end of a substantially vertically disposed connecting rod 284. The other end of the connecting rod 284 is pivotally secured to the bifurcated arm 286 of a bell crank 288. The bell crank 288 is pivotally mounted on the bell crank supporting stanchion 290 suspended from the track 232 of the horizontal label strip advancing carriage supporting platform 230 mounted on the main supporting standard 62. To firmly position the bell crank supporting stanchion 290, there is provided a horizontal supporting member 292 secured at one end to the main supporting standard 62 and at its other end to the lower portion of the bell crank supporting stanchion 290. The other arm 294 of the bell crank 288 terminates in a sector 296 which engages a rack 298 suspended from and mounted on the underside of the label strip advancing carriage 236. To rigidly position the roller 282 and the connecting rod 284 with respect to the slotted lever arm 274, a positioning member 300, pivotally secured at one end to the bell crank supporting stanchion 290 and pivotally secured at the other end to the connecting rod 284, is provided.

The arcuate movement of the slotted lever arm 274 resulting from rotation of the drive cam 46, as described above, results in vertical reciprocation of the connecting rod 284, which in turn results in a pivoting of the bell crank 288. The pivoting of the bell crank 288, through the engagement of the rack 298 by the sector 296, results in horizontal reciprocating movement of the label strip advancing carriage 236. The amplitude of arcuate movement of the free end of the slotted lever arm 274 is determined by the configuration of the cam track 262 for a cam follower lever arm 266 of given dimensions, and remains constant irrespective of the length of

label being operated upon and irrespective of the position of the main supporting standard 62.

As the bell crank supporting stanchion 290 is suspended from the track 232 of the horizontal label strip advancing carriage supporting platform 230, the bell crank 288 and the connecting rod 284 move relative to the slotted lever arm 274 together with the main supporting standard 62 whenever said standard 62 is shifted in position. The distance between the roller 282 within the slot 280 of the slotted lever arm 274 and the pivot end of said arm 274, i. e., the bifurcated mounting lug 276, determines the amplitude of vertical reciprocation of the connecting rod 284, which in turn determines the amplitude of horizontal reciprocation of the label strip advancing carriage 236. If the roller 282 is in the vicinity of the free end of the slotted arm 274, i. e., when the standard 62 is spaced relatively far from the center of the operating zone 84 (to accommodate a relatively long label), the amplitude of vertical reciprocation of the connecting rod 284 will be large, with an accompanying large amplitude of horizontal reciprocation for the second label strip advancing carriage 236, and, conversely, when the roller 282 is located in the vicinity of the pivoted end of the slotted arm 274, i. e., when the main supporting standard 62 is spaced relatively close to the center of the operating zone 84 (to accommodate a short label), the amplitude of vertical reciprocation of the connecting rod 284 will be small with an accompanying small amplitude of horizontal reciprocation for the reciprocating second label strip advancing carriage 236.

To aid in obtaining smooth and uniform movement of the label strip advancing carriage 236 in its reciprocating action, the bell crank 284 works against a spring 302 secured in tension between the crank 284 and an extended spring supporting member 304 mounted on the bell crank supporting stanchion 290.

Through the above described linkage, the amplitude of horizontal reciprocation of the second label strip advancing carriage 236 is automatically varied in accordance with the spacing of the main supporting standard 62, or stating it in another manner, is automatically varied in accordance with the length of label to be cut and folded.

The second label strip advancing carriage 236 is illustrated in its retracted position in Figs. 1, 2, 4, 5 and illustrated in a partially advanced position in Fig. 8. Its location in the retracted position, relative to the horizontal label strip advancing carriage supporting platform 230, remains the same irrespective of the spacing of the main supporting standard 62. However, the length of stroke of the label strip advancing carriage 236 towards the center of the operating zone 84 varies in accordance with the spacing of the standard 62.

The second label strip advancing carriage 236 is adapted to reciprocate in conjunction with the first label strip advancing carriage 146. Both the reciprocating carriages 146 and 236 move towards the center of the operating zone 84 simultaneously and with the same amplitudes of reciprocation. Both said carriages move away from the operating zone 84 simultaneously. Irrespective of the spacing of the standards 60 and 62, the retracted location of the carriages 146 and 236 with respect to their supporting platforms 244 and 230, respectively, remains the same. However, as explained above, the amplitudes of hori-

zontal reciprocation of said carriages vary in accordance with the spacing of the main supporting standards 60 and 62.

The above portion of the specification described the reciprocating motion of the carriage 236 and the general action of the label strip gripping jaws 238 and 240 mounted thereon. As explained at an earlier point in the specification, the label strip gripping jaws 238 and 240 are adapted to grasp, in gripping engagement, the end of the label strip after said strip has been advanced to the approximate center of the operating zone by the first label strip advancing carriage 146. After the jaws 238 and 240 have grasped the advanced portion of the label strip, the strip is advanced across the remaining portion of the operating zone 84 by the retraction of the carriage 236. After the carriage 236 has reached its fully retracted position, as illustrated in Fig. 1, the jaws 238 and 240 must be opened to release the label strip after said strip has been clamped, for further operations upon the advanced portion of the label strip.

To provide for the proper cyclic operation of the opening and closing of the label strip gripping jaws 238 and 240 irrespective of the spacing of the standards 60 and 62, said jaws 238 and 240 are provided with a separate driving linkage. It will be obvious from what has gone before that the jaws 238 and 240 must be closed to grasp the end of the label strip when the gripping ends of said jaws are located at the approximate center of the operating zone 84. As the amplitude of reciprocation of the carriage 236 varies in accordance with the spacing of the standards 60 and 62, the actuation of said jaws 238 and 240 is made independent of the spacing of said standards 60 and 62.

Referring now particularly to Figs. 1, 3, 4 and 9, and also to Fig. 12 which shows an oblique view of the essentials of the mechanical linkage for actuating the jaw member 238, the drive for opening and closing the pivotable jaw member 238 originates at the fixed drive cam 46 mounted on the main drive shaft 38. This is the same cam from which the drive for the second reciprocating carriage 236, described above, originates. The drive cam 46 is provided with a suitably shaped cam track 312 on the side of the cam 46 adjacent the main supporting standard 62. Contained within the cam track 312 is a rotatable cam follower 314 secured to one arm of a bifurcated cam follower lever arm 316. The cam follower lever arm 316 is pivotally mounted at one end on the fixed cam follower lever arm supporting shaft 58. Mounted on the free end of the cam follower lever arm 316 and positioned across the bifurcated portion thereof is a horizontally disposed shaft 318 of a length determined by the maximum length of stroke of the second label strip advancing carriage 236. The shaft 318 is mounted in spaced relationship from the surface of the cam follower lever arm 316 by the supporting members 320, 322. The shaft 318 is disposed within a slot 324 of a connecting member 326. Mounted at the other end of the connecting member 326 is a horizontally disposed shaft 328 rotatably suspended from the horizontal platform 230 by the brackets 327 and 329 (see Fig. 4). Mounted in spaced relationship on and turning with the shaft 328 is a bar 330 supported by the supporting members 332 and 334. The underside of the bar 330 is engaged by a suitably shaped roller 336 mounted at one end of a connecting rod 338. The other end of the connect-

ing rod 338 extends upwardly through a suitably placed aperture in the horizontal supporting platform 230 and is pivotally connected to the free end of the lever arm 248. As described above, the lever arm 248 is pivotally mounted on the lever arm supporting bracket 252 mounted on the reciprocating carriage 236. The lever arm 248 is in engagement with the stud 250 mounted on the movable jaw member 238 and depression of said lever arm 248 results in opening of the gripping ends of the jaw members 238 and 240.

Rotation of the drive cam 46 results in arcuate movement of the cam follower lever arm 316 about the cam follower lever arm supporting shaft 50. The arcuate movement of the bar 318 mounted on the free end of the cam follower lever arm 316 through engagement by the slot 324 results in arcuate movement of the connecting member 326. Since the connecting member 326 is rigidly secured to the shaft 328, arcuate movement of said connecting member 326 results in partial rotation of said shaft 328. Partial rotation of said shaft 328 results in arcuate movement of shaft 330. Arcuate movement of shaft 330 results in substantially vertical reciprocation of the connecting rod 338 which in turn results in arcuate pivotal movement of the lever arm 248 about the lever arm supporting bracket 252. The arcuate movement of the lever arm 248 about the lever arm supporting bracket 252 results in depression of the rear end of the movable jaw member 238 and the consequent pivoting action results in an opening of the gripping end of said member 238.

The actuation of the lever arm 248 is thus cyclically responsive to the shape of the cam track 312 on the drive cam 46. To provide for the transmission of the motions in response to the movement of the cam follower lever arm 316, irrespective of the location of the reciprocating carriage 236 thereto, and irrespective of the position of the main supporting standard 62, the roller 336 mounted on the end of the connecting rod 338 is adapted to move with respect to said bar 330 in conjunction with the reciprocating action of said carriage 236.

The drive cam 46, the cam follower lever arm 316, the connecting member 326, the shafts 328 and 330 remain fixed in location with respect to the base 10, other than movements resulting from rotation of the drive cam 46, irrespective of the location of the main supporting standard 62. The lever arm 248, the connecting rod 338 and the roller 336 change their location relative to the above mentioned fixed members during the reciprocating movement of the second label strip advancing carriage 236. However, the linkage between the shaft 330 and the roller 336 permits the transmission of the required movements irrespective of the location of the second label strip advancing carriage 236. Thus the movement of the cam follower lever arm 316 in response to rotation of the drive cam 46 is transmitted to the lever arm 248 irrespective of the position of said jaw members with respect to the drive cam 46 through the action of the roller 336 engaged by the bar 330. The cyclic operation of the lever arm 248 and resulting opening and closing of the label gripping jaw members 238 and 240 is thus controlled in its entirety by the shape of the cam track 312, irrespective of the location of said jaw members with respect to the main supporting standard 62, and irrespective of the spacing of the main supporting standard 62.

In operation of the machine, a roll of labels

having a suitable axle or shaft is inserted into the label roll supporting assembly with the axle or shaft contained within the axle-receiving slots 116 and 118 therein. The end of the roll 5 of labels is then threaded through the tensioning fingers 132 on the tensioning roll 128 in a predetermined manner and advanced upwardly and placed in feeding engagement on the surface of the first label strip advancing carriage 146 which, together with the second label strip advancing carriage 236, is in the retracted position. The slideable guiding member 148 is then placed in guiding relationship with the portion of the label strip maintained on the surface of 10 the first label strip advancing carriage 146. The feed finger 159 is placed in feeding engagement with the raised feeding abutment intermediate the labels on said strip. Rotation of the main drive shaft 38 and consequent rotation of the drive cams 42 and 48 mounted thereon results in simultaneous movement of the first label strip advancing carriage 146 and the second label strip advancing carriage 236 towards the center of the operating zone 84. The mechanical drive 15 linkages for each of the reciprocating carriages have been described above in detail. The movement of the first label strip advancing carriage 146 advances the end of the label strip to the approximate center of the operating zone 84. 20 When the label strip advancing carriages 146, 236 reach the end of their strokes in the vicinity of the approximate center of the operating zone 84, the label gripping jaws 238 and 240 mounted on the second label strip advancing carriage 25 35 close in gripping engagement on the advanced end of the label strip. On the return cycle of the carriages 146 and 236, the label strip is advanced across the remaining extent of said operating zone 84 through the continued 40 engagement by the gripping jaw members 238 and 240 and the retraction of said members together with the retraction of the second label strip advancing carriage 236. During the return cycle of the first label strip advancing carriage 45 146, said carriage moves in a direction opposite that of the still advancing label strip. When said carriages 146 and 236 reach their fully retracted position, the label strip is positioned across the operating zone 84 and maintained in 50 said position by the gripping action of the jaw members 238 and 240 and the back tension provided by the tensioning roll 128. The above described sequence of operations occurs irrespective of the spacing of the supporting standards 55 60 and 62 which determine the extent of the operating zone 84. Through the means included in the mechanical drive linkages for the label strip advancing carriages 146 and 236, described in detail above, the amplitudes of reciprocation or lengths of stroke of said carriages are automatically varied in accordance with the spacing of the standards 60 and 62. The cyclic operation of the jaw members 238 and 240 are determined solely by the configuration of the 60 cam track 312 on the drive cam 46 and remains the same irrespective of the spacing of said standards 60 and 62 and the amplitudes of reciprocation of the label strip advancing carriages 146 and 236.

(4) Clamping assembly

The label strip advancing assembly, described in the previous section of this specification, is provided to advance a label strip across the extent of the operating zone 84. A clamping as-

sembly is provided to securely clamp the advanced portion of said label strip, i. e., the portion disposed across the operating zone 84, while said advanced portion is being severed from the remainder of the label strip and to maintain the severed portion in continual clamped engagement as it is being introduced into the folding and pressing assembly by the clamping assembly. The presently preferred embodiment of the clamping assembly is best illustrated in Figs. 1, 2, 3, 7, 8 and 9. A skeletonized presentation of the essential elements of the clamping assembly and the drive therefor is illustrated in Figs. 16, 16a, 17 and 18. The clamping assembly is formed of two similar clamping units, one being associated with each of the main supporting standards 60 and 62.

To engage the upper surface of the advanced portion of the label strip adjacent the supporting standards 60 and 62, the horizontally disposed clamping members 346 and 348 are provided. The clamping member 346 is mounted at one end on a vertical clamping member actuating arm 350. For the purposes of clarity of explanation and ease of description, the surfaces of the main supporting standards 60 and 62 defining the extent of the operating zone 84 and facing the intermediate drive cam 44 will be defined as the "inner surfaces" of said standards. The surface of the main supporting standards 60 and 62 facing the drive cams 42 and 46, respectively, will be defined as the "outer surfaces" of said standards.

The clamping member actuating arm 350 is maintained in sliding engagement against the inner surface of the main supporting standard 60 and guided in its sliding movement by the channel blocks 354 and 356 mounted thereon. The clamping member 348 is secured at one end to a similar vertical clamping member actuating arm 352. The clamping member actuating arm 352 is maintained in sliding engagement against the inner surface of the main supporting standard 62 and is guided in its sliding movement by the channel blocks 358 and 360 (see Fig. 16). The clamping member actuating arms 350, 352 are slidably mounted adjacent the front end of the main supporting standards 60 and 62 and are positioned so that the advanced portion of the label strip and the members mounted on the label strip advancing carriages 146 and 236 pass beneath the horizontally extended clamping members 346 and 348 when said strip is advanced across the operating zone 84 during feeding operations.

Mounted on the underside of the clamping members 346 and 348 and along the length thereof are the plane label contact members 362 and 364, respectively (see Figs. 7 and 16a). Referring to Fig. 16a, which illustrates the clamping member 348 in cross section, it is seen that the contact member 364 extends horizontally beyond the main body portion of the clamping member 348 and towards the main supporting standard 62. The contact member 362 mounted on the clamping member 346 is similarly mounted and extends toward the supporting standard 60. The contact members are sized so that a predetermined amount of the advanced portion of the label extends outwardly beyond said contact members. This extended portion becomes the folded portion of the label. Hence, the edges of the contact members define the length of the folded label. The edges of the contact members 362 and 364 adjacent the supporting standards 60 and 62,

respectively, function as fold-forming or fold-directing edges when said clamping members are moved into engagement with the folding and pressing assembly, to be described in detail at a later point in this specification.

The clamping members 346 and 348 are adapted to be vertically reciprocated in the proper cyclic relationship during operation of the machine. During feeding operations, as described above in the preceding section of this specification, the clamping members 346 and 348 are maintained in the uppermost portion of their stroke and are disposed a sufficient distance above the surface of the horizontal supporting platforms 144 and 230 to permit the movement of the reciprocating label strip advancing carriages 146 and 236 and the members mounted thereon, therebeneath. After the label strip has been advanced across the operating zone 84 in the manner described above, the clamping members 346 and 348 are simultaneously moved downwardly until the contact members 362 and 364 mounted on the underside thereof engage the upper surface of the advanced portion of the label strip. The drive for said clamping members 346 and 348 will now be described in detail.

The drive for the clamping members 346 and 348 is illustrated in Figs. 1, 2, 3, 4 and 8. Fig. 16 is an oblique view of the essentials of the drive linkage for the clamping member 348 associated with the main supporting standard 62. Figs. 17 and 18 show the essentials of the drive for the clamping members.

The drive for the clamping members 346 and 348 originates at the intermediate drive cam 44 positioned between the supporting standards 60 and 62 and mounted on the main drive shaft 38. The intermediate drive cam 44 is provided with a suitably shaped cam track 370 on one side thereof. Contained within the cam track 370 is a rotatable cam follower 372 secured to one arm of a bifurcated cam follower lever arm 374. The cam follower lever arm 374 is pivotally mounted at one end on the fixed cam follower lever arm supporting shaft 46. A cylindrical sleeve 376 is rotatably mounted on a suitable shaft positioned between the arms of said bifurcated lever arm 374 on the free end thereof. Mounted on the cylindrical sleeve 376 is a vertical connecting rod 378. The vertical connecting rod 378 supports the center of a horizontally disposed shaft 380 which extends through suitable elongated vertically disposed shaft-receiving slots 382 and 384 contained in the main supporting standards 60 and 62 respectively.

The horizontal shaft 380 is of a length determined by the maximum extent of the operating zone 84. Slidably mounted on the outer surface of the main supporting standard 60 is a slideable spacing block 386. The block 386 is provided with a suitable aperture aligned with said shaft-receiving slot 382 in said standard 60, adapted to contain the portion of the horizontally disposed shaft 380 passing therethrough. The block 386 is securely connected to the clamping member actuating arm 350 slidably mounted on the inner surface of the standard 60 by a suitable fastening member passing through the slot 382. Slidably mounted on the outer side of the main supporting standard 62 is a slideable spacing block 388. The block 388 is provided with a suitable aperture, aligned with said shaft-receiving slot 384 in said standard 62, adapted to contain the portion of the horizontally disposed shaft 380 passing therethrough. The spacing block 388 is

securely connected to the clamping member actuating arm 352 slidably mounted on the inner surface of the standard 62 by a suitable fastening member passing through the slot 384.

Rotation of the intermediate drive cam 44, in response to rotation of the main drive shaft 38, results in a pivoting of the bifurcated cam follower lever arm 374 about the fixed cam follower lever arm supporting shaft 48. The amplitude of the arcuate movement through which the free end of said cam follower lever arm moves is determined by the shape of the cam track 372. The arcuate motion of the free end of the cam follower lever arm 374 is transmitted into substantially vertical reciprocation of the connecting rod 378 secured to the cylindrical rotatably mounted sleeve 376. Vertical reciprocation of the connecting rod 378 is accompanied by vertical reciprocation of the horizontally disposed shaft 380 mounted on the end thereof. Vertical reciprocation of the horizontally disposed shaft 380 within the vertically disposed shaft-receiving slots 382 and 384 in the main supporting members or standards 60 and 62 results in vertical reciprocation of the spacing blocks 386 and 388 slidably mounted on the outer surfaces of the main supporting standards 60 and 62, respectively. The vertical reciprocation of the spacing blocks 386 and 388 results in vertical reciprocation of the clamping member actuating arms 350 and 352 secured thereto respectively and slidably mounted on the inner surfaces of the standards 60 and 62. The vertical movement of the clamping member actuating arms 350 and 352 is guided by the channel blocks 354 and 356, 358 and 360, respectively, and, as the clamping members 346 and 348 are securely mounted on the extremities of the clamping member actuating arms 350 and 352, said clamping members 346 and 348 move in conjunction therewith.

The amplitude of vertical reciprocation of the clamping members 346 and 348 is determined by the extent of the arcuate movement of the free end of the bifurcated cam follower lever arm 374 which, in turn, is determined by the shape of the cam track 370 on the side of the intermediate drive cam 44.

The intermediate drive cam 44, the bifurcated cam follower lever arm 374, the vertically disposed connecting rod 378 and the horizontally disposed shaft 380 remain fixed in location with respect to the base 10, other than changes in location resulting from rotation of the intermediate drive cam 44, irrespective of the spacing of the main supporting standards 60 and 62. The clamping members 346 and 348, the clamping members actuating arms 350 and 352 and the spacing blocks 386 and 388 are mounted on said main supporting members 60 and 62 and hence change their position relative to the fixed members set forth above whenever the spacing of the main supporting standards 60 and 62 is varied. A shifting of the spacing of the main supporting standards 60 and 62 shifts the relative location of the spacing blocks 386 and 388 on the horizontally positioned shaft 380. The apertures in the spacing blocks 386 and 388 are made slightly larger than the shaft 380 to permit said blocks to move relative to said shaft 380 whenever the spacing of the supporting standards 60 and 62 is varied. Through the above described drive linkage, the clamping members 346 and 348 will be vertically reciprocated independent of the spacing of the supporting

5 standards 60 and 62. The amplitudes of the vertical reciprocation and the cyclic operation of the clamping members 346 and 348 is determined solely by the shape and configuration of the cam track 370 on the side of the intermediate main drive cam 44 for drive linkage members of given dimensions.

10 The above described portion of the clamping assembly provides for the placing of the contact members 362 and 364 into engagement with the upper surface of the advanced portion of the label strip, i. e., that portion of the label strip disposed across the extent of the operating zone 84. Coacting with the above described clamping members 346 and 348 are pressure members adapted to be placed into engagement with the lower surface of the advanced portion of the label strip at locations substantially coincident with the point of contact of the contact members 362 and 364 mounted on the clamping members 346 and 348, respectively, whereby each end of the advanced portion of the label strip is clamped between the contact member mounted on its respective clamping member and its associated pressure member.

15 The pressure members utilized in the clamping assembly, in the presently preferred embodiment of the invention as illustrated in the drawings, are an integral element of the folding and pressing assemblies and perform a dual function. First, the pressure members function, during clamping operations, as an integral part of the clamping assembly, and second, function as an integral part of the folding and pressing assembly during the folding and pressing operations.

20 Fig. 17 is a view from the center of the operating zone 84 looking towards the main supporting standard 62. As such, it illustrates the mounting of the pressure member associated with the clamping member 348. It should be kept clearly in mind that the main supporting standard 60 supports a similarly mounted and positioned pressure member associated with the clamping members 346. Figs. 18 and 19 illustrate the relationship of the pressure members to the folding and pressing units forming the folding and pressing assembly. Figs. 34 and 35 illustrate the essentials of one of the folding and pressing units.

25 The folding and pressing units mounted on and supported by each of the main supporting standards 60 and 62 are adapted to reciprocate horizontally together in the plane of each of said supporting members during folding and pressing operations. However, during clamping operations, the folding and pressing units are positioned beneath the clamping members 346 and 348 (as illustrated in Fig. 17), and for the purpose of simplicity, the mechanical drive for horizontally reciprocating the folding and pressing units will be described in Section 7 of this specification. For the remainder of this description of the clamping assembly, it will be assumed that the folding and pressing units are at that point of their cycle of movements where they are positioned beneath the clamping members 346 and 348.

30 For the purposes of simplicity and brevity, the portion of the specification immediately following relating to the description of the structure and functioning of the pressure members will be based largely upon the pressure member associated with the clamping member 348 as illustrated in Fig. 17, it being kept clearly in mind that a similar construction is provided for the

pressure member associated with the clamping member 346 mounted on the main supporting standard 60.

Referring mainly to Fig. 17 and also to Figs. 18, 19, 20, 34 and 35, the pressure member 398 associated with the clamping member 348 and the pressure member 400 associated with the clamping member 346 each comprise a flat substantially rectangular member slidably disposed within the housings 402 and 404, respectively, of the folding and pressing units and positioned adjacent the inner surfaces of the main supporting standards 60 and 62. During clamping operations, the housings 402 and 404 of the folding and pressing units are positioned beneath the horizontal extended clamping members 348 and 346, as illustrated in Fig. 17, for the housing 402 and the clamping member 348. The pressure members 398 and 400 are adapted to be placed in contact with the underside of the advanced portion of the label strip at a location substantially coincident with the point of contact of the contact members 362 and 364 mounted on the underside of the clamping members 346 and 348. The action of the pressure members 398 and 400 in cooperation with the clamping members 348 and 346, described above, serve to securely clamp the advanced portion of the label strip in the vicinity of the supporting standards 60 and 62. The pressure members 398 and 400 are adapted to be vertically reciprocated within the housings 402 and 404 of the folding and pressing units.

The drive for vertically reciprocating the pressure members 398 and 400 originates at the intermediate drive cam 44 mounted on the main drive shaft 38 intermediate the main supporting members 60 and 62 (see Figs. 17 and 18). A suitably shaped cam track 405 on the surface of the intermediate drive cam 44 is utilized to control and direct the cyclic operation of the pressure members 398 and 400. Operatively engaged with and biased against the surface cam track 405 of the intermediate drive cam 44 by a spring 407 is a rotatable cam follower 406 mounted between the arms of a bifurcated cam follower lever arm 408. The bifurcated cam follower lever arm 408 is pivotally mounted at one end on the fixed cam follower lever arm supporting shaft 50. A cylindrical sleeve 410 is rotatably mounted on a suitable shaft positioned between the arms of said bifurcated cam follower lever arm 408 on the free end thereof. Mounted on the cylindrical sleeve 410 is a substantially vertically disposed connecting rod 412. The vertical connecting rod 412 supports the center of a horizontally disposed shaft 414 which extends through suitable elongated vertically disposed shaft-receiving slots such as the slot 416 in the standard 62. A similar slot 418 is provided in the main supporting standard 60 (see Fig. 2). The horizontal shaft 414 is of a length determined by the maximum extent of the operating zone 84 (referring now particularly to Figs. 17-19). Mounted on the inner surface of the main supporting standard 62 and provided with a suitable aperture for slidably encompassing the shaft 414 is a connecting member 420, a correspondingly shaped and positioned member 421 being mounted on the inner surface of the main supporting standard 60 (see Fig. 19). The other end of the connecting member 420 is pivotally secured to one end of an elongated slotted lever arm 422 which is pivotally mounted at its other end 424 on the main supporting standard 62. Contained within the slot 426 of the lever arm 422 is a roller 428 rotat-

ably mounted on the lower extremity of the pressure member 398. Similarly positioned on the main supporting standard 60 is a slotted lever arm 423 having a roller 429 mounted on the lower extremity of the pressure member 400 contained within the slot thereof (see Fig. 19).

Rotation of the intermediate drive cam 44 in response to the rotation of the main drive cam 38 results in a pivoting of the bifurcated lever arm 408 about the fixed cam follower lever arm supporting shaft 50. The amplitude of arcuate movement through which the free end of said cam follower lever arm 408 moves is determined by the shape of the surface cam track 405 of the intermediate drive cam 44. The arcuate motion of the free end of the cam follower lever arm 408 is transmitted into substantially vertical reciprocation of the connecting rod 412 secured to the cylindrical rotatably mounted sleeve 410. Vertical reciprocation of the connecting rod 412 is accompanied by vertical reciprocation of the horizontally disposed shaft 414 mounted on the end thereof. Vertical reciprocation of the horizontally disposed shaft 414 within the vertically disposed shaft-receiving slots 416 and 418 in the main supporting members or standards 60 and 62 results in arcuate motion of the end of the slotted lever arms 422 and 423 about their pivotal mountings. The arcuate motion of the ends of the slotted lever arms 422 and 423, through the engagement of the slots therein by the rollers 428 and 429, results in vertical reciprocation of the pressure members 398 and 400.

As the horizontal shaft 414 moves upwardly, the pressure members 398 and 400 are moved upwardly into clamping engagement with the underside of the advanced portion of the label strip at a location substantially coincident with the point of contact of said clamping members 346 and 348. The above action results in a secure clamping of the advanced portion of the label strip adjacent the ends thereof between the clamping members 346 and 348 and their respective pressure members 400 and 398.

The intermediate drive cam 44, the bifurcated cam follower lever arm 408, the vertically disposed connecting rod 412 and the horizontally disposed shaft 414 remain fixed in location with respect to the base 10, other than for changes in location resulting from rotation of the intermediate drive cam 44, irrespective of the spacing of the main supporting standards 60 and 62. The pressure members 398 and 400, the slotted lever arms 422 and 423 and the connecting members 420 and 421, being mounted on or associated with the main supporting standards 60 and 62, change their position relative to the fixed members set forth above whenever the spacing of the main supporting standards 60 and 62 is varied. A change in spacing of the main supporting standards 60 and 62 shifts the position of the connecting members 420 and 421 on the horizontally disposed shaft 414. The shaft-receiving apertures in said connecting members 420 and 421 are made slightly larger than the shaft 414 to permit said members to move relative to said shaft 414 whenever the spacing of the supporting standards 60 and 62 is varied. Through the above described linkage, the pressure members 398 and 400 will be vertically reciprocated independent of the spacing of the supporting standards 60 and 62. The amplitude of the vertical reciprocation and the cyclical operation of the pressure members 398 and 400 are determined by the shape and configuration of the surface cam track of the inter-

mediate drive cam 44 for drive linkage members of given dimensions.

As the label strip is being advanced across the label operating zone by the label strip advancing carriages 145 and 236, described above in the preceding section of the specification, the clamping members 346 and 348 are positioned at the uppermost portion of their cycle. In this position, the horizontally disposed clamping members 346 and 348 are located above the horizontal supporting platforms 144 and 230 mounted on the upper portion of the main supporting standards 60 and 62, respectively. The clamping members 346 and 348 are positioned a sufficient distance above said platforms 144 and 230 to permit the movement of the reciprocating carriages 146 and 236 and the members mounted thereon, therebeneath. After the label strip has been advanced across the extent of the operating zone and is maintained taut in the advanced position by the label gripping jaws 238 and 240 and the tensioning roll 128, the clamping members 346 and 348 are moved downwardly into engagement with the upper surface of said advanced portion of the label strip. During the downward motion of the clamping members 346 and 348, the pressure members 398 and 400 are moved upwardly by the mechanical drive linkage, described above. The amplitudes of the strokes of clamping members 346 and 348 and the pressure members 398 and 400 are of a predetermined value such that each clamping member and its respective pressure member securely clamps the portions of the advancing label strip adjacent the supporting standards 60 and 62. Following the clamping operation, the advanced clamped portion of the label strip is securely clamped adjacent its ends and maintained in said clamped engagement while said advanced portion is severed from the remainder of the label strip. It should be noted at this point that the advanced portion of the label strip is always clamped adjacent the supporting standards 60 and 62 and hence irrespective of the length of label to be cut and folded, said advanced portion is positively clamped adjacent its extremities.

(5) *Cutting assembly*

The above portions of the specification describe the construction and mode of operation of the label strip advancing assembly and the clamping assembly. The label strip advancing assembly serves to advance a label strip across the extent of the operating zone 84. After the label strip has been advanced across the extent of the operating zone 84, the advanced portion thereof is clamped by the clamping assembly. To sever the clamped, advanced portion of the label strip from the remainder of the label strip, a cutting assembly is provided. Referring to Figs. 1, 2, 5, 7 and 8, a movable blade member 442 is pivotally mounted in cutting relationship with a fixed blade member 444 mounted on the upper portion of the horizontal supporting platform 144 adjacent the edge of the operating zone 84 on the main supporting standard 60. The movable blade member 442 is supported at one end by a suitable lug mounted on the fixed blade member 444. As the blade member 444 is fixedly mounted on the horizontal supporting platform 144 and moves therewith, the movable blade member 442 is actuated independent of the spacing of the supporting standards 60 and 62.

To provide for the proper cyclic actuation of the cutting assembly, independent of the spacing of the main supporting standard 60, the movable

blade member 442 is provided with a separate driving linkage.

Referring now particularly to Figs. 4, 5, 6 and 10 and also to Fig. 15 which shows an oblique view of the essentials of the mechanical drive linkage for actuating the movable blade member 442, the drive for actuating the movable blade member 442 originates at the fixed drive cam 42 mounted on the main drive shaft 38 and positioned between the main supporting standard 60 and the drive pinion 40. This is the same drive cam from which the drive for the first reciprocating carriage 146, described above, originates. The drive cam 42 is provided with a suitably shaped cam track 446 on the side of the cam 42 adjacent the drive pinion 40. Contained within the cam track 446 is a rotatable cam follower 448 secured to one arm of a bifurcated cam follower lever arm 450. The cam follower lever arm 450 is pivotally mounted at one end on the fixed cam follower lever arm supporting shaft 50. Mounted on the movable end of the cam follower lever arm 450 and positioned across the bifurcated portion thereof is a horizontally disposed shaft 452, of a length determined by the length through which the main supporting standard 60 may be moved. The shaft 452 is mounted in spaced relationship adjacent the body of the cam follower lever arm 450 by the supporting members 454 and 456. The shaft 452 is disposed within a shaft-receiving slot 458 positioned at one end of a connecting member 460. Mounted on the other end of the shaft 452 is a horizontally disposed shaft 462 rotatably mounted above the horizontal supporting platform 144 in a suitable mounting member 484, (see Fig. 5). The horizontal supporting platform 144 is provided with a suitably placed aperture to permit the passage of the connecting member 460 therethrough. Mounted on the other end of the shaft 452 is a lever arm 466. The other end of the lever arm 466 is connected to a link 468 by a suitable connecting pin 470 (see Figs. 5, 7 and 15). The link 468 is provided with a bifurcated end portion having the end of the movable blade member 442 pivotally mounted therein.

Rotation of the drive cam 42 results in arcuate movement of the cam follower lever arm 450 about the cam follower lever arm supporting shaft 50. The arcuate movement of the shaft 452 mounted on the free end of the cam follower lever arm 450 through engagement by the slot 458 results in arcuate movement of the connecting member 460 about the shaft 462. Arcuate movement of said connecting member 460 results in partial rotation of said shaft 462. Partial rotation of said shaft 462 results in arcuate movement of the free end of the lever arm 466. Arcuate movement of the free end of the lever arm 466 results in substantially vertical reciprocation of the link 468. Vertical reciprocation of the link 468 results in a pivoting of the movable blade member 442 about the mounting lug secured to the end of the fixed blade member 444. As the movable blade member 442 is pivotally mounted about the above mentioned supporting lug mounted on the fixed blade member 444, the cutting edge of said movable member 442 engages the cutting edge of the fixed member 444 in cutting relationship. The above movement of the movable blade member 442 with respect to the fixed member 444 may be described as a scissor-like cutting action.

The actuation of the movable blade member 442 is cyclically responsive to the shape of the

cam track 446 on the drive cam 42. To provide for the transmission of the above required motion in response to the movement of the cam follower lever arm 450, irrespective of the location of the main supporting standard 60, the slotted connecting member 460 is adapted to move in relation to the shaft 452 whenever the main supporting standard 60 is shifted in position. The drive cam 42, the cam follower lever arm 450, and the shaft 452 remain fixed in location with respect to the base 10, other than movements resulting from rotation of said drive cam 42, irrespective of the location of the main supporting standard 60. The cutting members 442 and 444, the link 468, the lever arm 466, the shaft 462 and the connecting member 460, being directly connected to the main supporting standard 60, i. e., said fixed blade member 44 being mounted on said horizontal supporting platform 144, change their location relative to the above mentioned fixed members whenever said main supporting standard 60 is shifted in position. However, the linkage between the slot 458 and the shaft 452 permits the transmission of the required movements irrespective of the location of the main supporting standard 60. Thus the movement of the cam follower lever arm 450 is transmitted to the connecting member 460 irrespective of the location of said slot on said shaft 52. The cyclic operation of the movable blade member 442 is thus controlled in its entirety by the shape of the cam track 446 irrespective of the location of said main supporting standard 60.

(6) *Label trimming assembly*

In some instances, a roll of labels is defective in that the identifying indicia on the individual labels is not symmetrically disposed between and with respect to the raised feeding abutments. In such instances, the indicia may be centered on the folded label by varying or adjusting the amount of fold at the ends of the label. However, in so doing, the length of fold at each end of the label will then be unsymmetrical, i. e., the fold at one end of the label will be longer than the fold at the other end.

Included in this invention are means by which labels whose identifying indicia is unsymmetrically disposed with respect to the feeding abutments, may be trimmed prior to the introduction of the severed label into the label operating components to provide a label whose identifying indicia is centered with respect to the folded edges and whose folded portions are of equal length. This includes a mechanism, now to be described, for trimming the leading edge of the labels and a manual adjustment in the drive linkage for the first label strip advancing carriage 146 for regulating the location of the cut on the trailing edge of the labels.

At an earlier point in this specification, i. e., Section 3 describing the label strip advancing assembly, the means included in the driving linkage for the first label strip advancing carriage 146 for permitting movement of said carriage through a small distance, independent of the main driving linkage, through rotation of the bell crank 263 independent of the bell crank 203 (see page 25, et seq.) was described.

The means for trimming the leading edges of unsymmetric labels may be briefly described as including means by which the first label strip advancing carriage 146 may be advanced, intermediate label feeding operations, a distance equal

to the amount of label desired to be trimmed and a cutting of said advanced portion by the above described cutting assembly. The driving linkage for operation of the cutting assembly has been described above in detail. It was there stated that the cyclic operation of the movable cutting member 442 was controlled by the shape of the cam track 446 irrespective of the location of the main supporting standard 60. The cam track 446 is shaped to cyclically actuate the movable blade member 442 twice during each complete cycle of operation. The first cutting action severs the advanced portion of the label strip, i. e., that portion disposed across the operating zone 64, from the remainder of the label strip. On its second cutting action, it is adapted to sever a small portion of the end of the label strip disposed in feeding engagement upon the surface of the first label strip advancing carriage 146 if a trimming of the edge of the label strip is desired. The amount of label that is trimmed on the second cut of the movable blade member 442 is determined by the distance through which the first label strip advancing carriage 146 is advanced during the trimming segment of the cycle of operations. Of necessity, the degree of advance of the label strip advancing carriage 146 during the trimming segment of the cycle of operations must be made adjustable so that the amount of trim of the leading edge of the labels may be regulated and controlled by the operator of the machine in accordance with the particular unsymmetric labels being operated upon. As mentioned at an earlier point in this specification, the mechanical drive linkage for the first label strip advancing carriage 146 permitted independent movement of said carriage 146 in addition to the movements resulting from said main drive linkage during label strip feeding operations. The mechanical drive linkage for advancing the label strip advancing carriage 146 during trimming operations is best illustrated in Figs. 4 and 5 and a detailed view of the essentials of the trimming drive linkage mechanism is shown in Fig. 14.

The drive for advancing the first label strip advancing carriage 146 during the trimming operation on the leading edge of the labels originates at the fixed drive cam 42 mounted on the main drive shaft 38 adjacent the main drive shaft pinion 49. A suitably shaped cam track 480 on the surface of the drive cam 42 is utilized to control and direct the cyclic operation of the trimming mechanism. Operatively engaged with the surface cam track 480 of the drive cam 42 is a rotatable cam follower 482 mounted between the arms of a bifurcated cam follower lever arm 484. The bifurcated cam follower lever arm 484 is pivotally mounted at one end on a fixed cam follower lever arm supporting shaft 486. The cam follower lever arm supporting shaft 486 is supported in a mount 488 positioned on the upper surface of the main drive system supporting member 20 (see also Fig. 4). The free end of the cam follower lever arm 484 supports a horizontally disposed platform 490. Riding on the surface of the platform 490 is a roller 492 mounted between the bifurcated arms 484 of a substantially vertically disposed connecting member connected to a substantially horizontally disposed pivoted lever arm 496. The lever arm 496 is pivotally supported at one end by a suitable mounting member positioned on the outer surface of the main supporting standard 60. The free end of the lever arm 496 has mounted thereon an adjustable thumbscrew 498. The thumb-

screw 498 is positioned so as to engage an extended arm 500 which is connected to the bell crank 208.

Rotation of the drive cam 42 in response to rotation of the main drive shaft 38 results in arcuate movement of the free end of the bifurcated cam follower lever arm 484. The arcuate movement of the free end of said cam follower lever arm 484 results in arcuate movement of the lever arm 496 through the engagement of the 10 roller 492 by the platform 490. The arcuate movement of the free end of the lever arm 496 is transmitted to the bell crank 208 by the thumbscrew 498 through the arm 500. Thus arcuate motion of the free end of the cam follower lever arm 484 results in rotative movement 15 of the bell crank 208. The rotative movement of the bell crank 208 through the engagement of the rack 216 by the sector 214 results in an advancement of the first label strip advancing carriage 146. The advancement of the label strip advancing carriage 146 is, of necessity, of small amplitude. However, it should be clearly kept in mind that the trimming operations will only necessitate the cutting off of a small portion of the end 20 of the label strip. The amount of advance of the label strip advancing carriage 146 during trimming operations may be controlled by adjusting the spacing between the end of the thumbscrew 498 and the arm 500. The above 30 construction permits the trimming of the leading edge of the labels in the label strip. The trimming of the trailing edge of the labels may be adjusted by controlling the length of advance of the first label strip advancing carriage 146 by varying the spacing between the arm 205 of the bell crank 203 and the arm 212 of the bell crank 208 through adjustment of the thumbscrew 207.

The above described drive linkage thus permits a relatively small and adjustable advance, for leading edge trimming purposes, of the first label strip advancing carriage 146. The length of advance of said carriage 146 may be adjusted in accordance with the amount of label desired to be trimmed. This, of course, depends upon the degree of displacement of the identifying indicia with respect to the raised feeding abutments for any particular roll of labels.

The shape of the surface cam track 480 of the drive cam 42 controls the cyclic advancement of the first label strip advancing carriage 146 during trimming operations. The movable blade member 442 is actuated, during the trimming operations, on its second cut per cycle by the shape of the cam track 448 on the side of the main drive cam 42. Thus, the timing of the trimming operations depends entirely upon the shape of the respective cam tracks of the drive cam 42.

The cycle of trimming operations occurs independently of the spacing of the main supporting standard 60. The drive cam 42, the cam follower lever arm 484, and the platform 490 mounted on the end thereof, are fixed in position other than for movements relating to rotation of said drive cam 42, irrespective of the spacing of the main supporting standard 60. The lever arm 496, the roller 492 and the arm 500, together with the bell crank 208, are all mounted on and move together with the main supporting standard 60. Thus, whenever said main supporting standard 60 is shifted in position, the point of engagement of the roller 492 on the surface of the platform 490, shifts in accordance therewith, and hence, irrespective of the spacing of said main supporting standard 60, the above described mechanical 75

linkage transmits the movements in response to rotation of the main drive cam 42 to the first label strip advancing carriage 146.

In normal operations handling symmetric label strips, the adjusting thumbscrew 498 is backed off a sufficient amount to render the label trimming assembly inoperative for trimming the leading edge of the label strip.

(7) *Folding and pressing assembly*

The cutting assembly described above in Section 5 serves to sever the advanced clamped portion of the label strip disposed across the top of the operating zone 84 from the remainder of the label strip. Prior to and during the cutting operations, the advanced portion of the label strip is securely clamped adjacent its ends by the action of the clamping assembly. As described above in Section 4 of this specification, the clamping assembly including the horizontally extending clamping members 346 and 348 having the contact members 362 and 364 mounted thereon and adapted to engage the upper surface of the advanced portion of the label strip and the pressure members 398 and 400 which are adapted to compressively clamp the under surface of the advanced portion of the label strip against said contact members. The pressure members 398 and 400 were there stated to be an integral part of the folding and pressing units forming the folding and pressing assembly, which, during clamping operations, are positioned beneath the clamping members 346 and 348. The edges of the contact members 362 and 364 extending towards the inner surfaces of the main supporting standards 60 and 62 function as fold-forming or fold-directing edges during the folding operations. The clamping assembly is so positioned that the ends of the clamped advanced portion of the label strip extend a predetermined distance beyond the fold-forming or fold-directing edges of the contact members 362 and 364 and this extended portion of the label strip becomes the folded-under portion of the label.

After the advanced clamped portion of the label strip has been severed from the remainder of the label strip, the clamping assembly, while maintaining the severed portion in secure clamped engagement, moves downwardly to lower the severed label into engagement with the folding and pressing assembly, which is positioned directly below the clamping members 346 and 348 during this portion of the cycle of operation. The mechanical drive for the clamping assembly, i. e., the drive for vertically reciprocating the clamping members 346 and 348, and the drive for vertically reciprocating the pressure members 398 and 400 has been described above in detail in Section 4 of this specification and in their downward movement move together and continually maintain the severed label in clamped relationship.

The folding and pressing assembly may generally be described as comprising a pair of similar units, one being associated with each of the main supporting standards 60 and 62, and each unit having a pivoted folding arm, actuated by a cam member included in and reciprocable with the clamping assembly, which cooperates with the fold-forming edges of the contact members 362 and 364 of the clamping assembly to form the fold in the severed label. The end portions of the clamped severed label extending beyond the clamping members engage the upper surface of the folding arms in the course of their downward movement and are bent upwardly and partially

over the fold-forming edges of the contact members 362 and 364. When the clamped severed portion of the advanced label strip is lowered completely into the folding and pressing assembly, the folding arms are pivoted and fold the now upwardly disposed end portions of the severed label over the edges of the contact members 362 and 364. The folding and pressing assembly is then moved as a unit together with the now folded label horizontally out of engagement with the contact members 362 and 364 mounted on the clamping members 346 and 348 and into operative relationship with the stacking assembly. After the folding and pressing assembly has moved completely out of engagement with the contact members 346 and 348, the pressure members 398 and 400 are again moved upwardly by the drive linkage described above in Section 5 of this specification and press the fold in the label against the undercut portions of the folding arms. Suitable heating elements are mounted on the folding arms to aid the pressure members in forming a sharp crease along the length of the fold. After the fold in the label has been pressed, the stacking assembly removes the folded and pressed label from the folding and pressing assembly and the folding and pressing assembly is then moved horizontally back into label-receiving position beneath the clamping members.

The folding and pressing assembly is best illustrated in Figs. 17, 19, 20, 34 and 35. Figs. 17 and 20 illustrate a single folding and pressing unit mounted on one of the main supporting standards, but it should be kept clearly in mind that a corresponding construction and arrangement is provided for the other folding and pressing unit mounted on the other main supporting standard. Included in each of the folding and pressing units, i. e., one unit being mounted on each of the main supporting standards 60 and 62, is an external housing, such as the housings 402 and 404 (see Figs. 19, 34 and 35). Slidably contained within the housings 402 and 404 are the vertically disposed pressure members 398 and 400 which were described in detail above together with the mechanical drive therefore, in Section 4 of this specification. The housings 402 and 404 are secured to and supported by the horizontally disposed slideable shafts 510 and 512, respectively (see also Figs. 1, 2, 3, 6, 8, 9 and 10). The shafts 510 and 512 are slidably supported on the outer surfaces of the main supporting standards 60 and 62 which are provided with suitable cut out portions to permit the horizontal reciprocating movement of the folding and pressing units (see Fig. 17). Suitable channeled guiding blocks, such as 513 in Fig. 2, are provided to maintain the horizontal shafts 510 and 512 suitably positioned. Included in each of the folding and pressing assemblies is a substantially vertically disposed folding arm, such as the folding arms 514 and 516 (see Fig. 19). The folding arms 514 and 516 are supported by and pivoted about the shafts 513 and 520. The folding arms 514 and 516 are normally maintained in their forward or folding position as illustrated in Fig. 19.

The drive for pivoting the folding arms 514 and 516 from their forward position to their retracted position is illustrated in Fig. 20 which illustrates the folding and pressing unit associated with the main supporting standard 62. The following description will be limited to the construction there shown, with the understanding that a similar construction is provided for the folding and pressing assembly unit associated with the main support-

ing standard 60. Suitably positioned on the lower portion of the folding arm 514 and supported by lugs 522 and 524 is a shaft 526. The shaft 526 extends beyond the housing 402 and mounted on said extended portion is a roller 528. The pivotal movement of the folding arm 514 is controlled by the plate 530 mounted on the upper portion of the spacing block 388 (see Figs. 2, 18, and 20) included in the clamping assembly. The plate 530 is provided with two suitably located inclines 532 and 534 adapted to engage the roller 528 during the vertical reciprocation of the clamping assembly. When the clamping member 348 is at the uppermost portion of its cycle, i. e., disposed above the line of advance of the label strip across the extent of the operating zone 34, the folding and pressing unit is positioned beneath said clamping member. The plate 530 is positioned above the roller 528 and the folding arm 514 is in its forward or folding position. After the clamping member 348 initiates its downward movement to clamp the now advanced portion of the label strip, the corresponding downward movement of the plate 530 brings the incline 534 into engagement with the roller 528, and the resulting cam action pivots the folding arm 514 about its mounting on the shaft 518 and moves said member from its forward or folding position to its retracted position. This is required in order to permit the pressure member 398 to be moved vertically upward past the folding arm while said pressure member 398 is functioning as part of the clamping assembly. The surface of the plate 530 maintains the folding arm 514 in its retarded position throughout the clamping and cutting operations. After the advanced clamped portion of the label strip has been severed from the remainder of the label strip, the clamping assembly, maintaining the severed label in secure clamped engagement, is moved downwardly until the contact member 364, mounted on the underside of the clamping member 348 is resting upon or is closely adjacent to the upper surface of the housing 402 of the folding and pressing unit. The incline 532 is suitably located on the plate 530 so as to permit the roller 528 to be engaged therewith to permit the folding arm 514 to pivot about its shaft 518 and to return into its forward or folding position over the contact member 364.

During the downward movement of the advanced clamped severed portion of the label strip, the portions thereof extending beyond the edge of the contact members 364 and 366 engage the upper surfaces 536 and 538 of the retracted folding arms 514 and 516 and said end portions are bent upwardly with relation to the fold-forming edges of the contact members 362 and 364, respectively. After the contact members 362 and 364 are moved to their lowest position, i. e., resting on or adjacent to the upper surfaces of the housings for the folding and pressing units, the above described cam action of the incline 532 and its corresponding member associated with the other main supporting standard in returning the folding arms 514 and 516 to their forward position results in a folding of said upwardly bent portions of the label strip over the contact members 362 and 364 by the undercut portions 540 and 542 of said folding arms 514 and 516.

The above sequence of clamping, cutting and folding operations is schematically illustrated in Figs. 24 to 29, inclusive. Figs. 24 through 29 are not to be taken as being representative of dimensions or proportions of various structures but are solely included for the purpose of schematically

illustrating the sequence of operations. Fig. 24 illustrates the clamping action of the clamping members 346 and 348 and the coacting pressure members 398 and 400 as they move towards the advanced portion of the label strip. During this portion of the cycle, the folding arms 514 and 516 are in their retarded position as is necessitated by the fact that the pressure members 398 and 400 are being moved upwardly.

Fig. 25 illustrates the advanced portion of the label strip in its clamped position and also shows the first cut of the movable blade member 442 severing the advanced clamped portion of the label strip from the remainder of the label strip.

Fig. 26 illustrates the advanced clamped portion of the label strip immediately after said portion has been severed from the remainder of the label strip and the opening of the jaw members 238 and 240 following the cutting operation.

Fig. 27 illustrates the downward movement of the clamping members 346 and 348 and the pressure members 398 and 400 after the cutting operation. During the downward movement of the advanced severed portion of the label strip, said portion is continuously maintained in a secure clamped engagement by the clamping members 346 and 348 and the coacting pressure members 398 and 400. Throughout the above series of operations, the folding arms 514 and 516 are maintained in their retarded position.

Fig. 28 illustrates the folding action. During the downward movement of the advanced clamped severed portion of the label strip, the extended portions thereof 544 and 546 contact the upper surfaces 536 and 538 of the folding arms 514 and 516, respectively, and are bent upwardly, as illustrated in the drawings. The positive clamping action is continually maintained.

In Fig. 29, the clamping members 346 and 348 have been lowered to a point which permits the folding arms 514 and 516, through the above described cam action to be moved into their forward or folding position and fold the extended portions 544 and 546 of the label strip over the fold-forming edges of the contact members 362 and 364, respectively. The above described series of events completes the fold in the advanced, severed portion of the label strip. After the fold is formed, the pressure members 398 and 400 are moved downwardly and the label is maintained in the folding and pressing assembly by the action of the folding arms 514 and 516. It should be noted at this point that the undercut portions 540 and 542 of the folding arms 514 and 516, respectively, are positioned over the contact members 362 and 364 of the clamping members 346 and 348, respectively. In such position, it is obvious that the clamping members cannot be moved upwardly and out of engagement with the folding and pressing assembly.

As stated above at an earlier point in this specification, the folding and pressing units in the folding and pressing assembly are adapted to reciprocate horizontally with respect to the main supporting standards 60 and 62. As such, the folding and pressing assembly with the pressure members 398 and 400 withdrawn from compressive engagement with the contact members 362 and 364, together with the now folded label is horizontally moved out of engagement with the clamping members 346 and 348, a suitable abutment being provided on the upper surface of the housings 402 and 404 to engage the edge of the label and move it together with the folding and

pressing units horizontally out of engagement with the clamping members 346 and 348.

Referring to Fig. 17, the drive for horizontally reciprocating the folding and pressing units originates at the intermediate drive cam 44 mounted on the main drive shaft 38 intermediate the supporting standards 60 and 62. The intermediate drive cam 44 is provided with a suitable shaped cam track 550 on one side thereof. Contained within the cam track 550 is a cam follower 552 rotatably mounted on one arm of a bifurcated cam follower lever arm 554. The cam follower lever arm 554 is pivotally mounted at one end on the fixed cam follower lever arm supporting shaft 50. Mounted on the free end of the cam follower lever arm 554 is a horizontally disposed shaft 556 which extends beyond the main supporting standards 60 and 62 through suitably cut-out portions thereof. As Fig. 17 only illustrates the folding and pressing unit associated with the main supporting standard 62, the remainder of the description of the drive linkage will refer solely to the linkage there shown but it should be understood that corresponding units are provided for the folding and pressing unit associated with the main supporting standard 60. Slidably mounted on the shaft 556 and positioned adjacent the outer surface of the main supporting standard 62 is a substantially vertically disposed connecting member 560. Pivotally connected to the end of the vertical connecting member 560 and pivotally secured to the housing 402 of the folding and pressing unit associated with the main supporting standard 62 is a connecting link 562.

Rotation of the intermediate drive cam 44 in response to rotation of the main drive shaft 38 results in a pivoting of the bifurcated cam follower lever arm 554 about the fixed cam follower lever arm supporting shaft 50. The amplitude of arcuate movement through which the free end of said cam follower lever arm 554 moves is determined by the shape of the cam track 550. The arcuate motion of the free end of the cam follower lever arm 554 and of the horizontally disposed shaft 556 mounted thereon results in similar motion of the connecting rod 560 slidably mounted on said shaft 556. The arcuate motion of the free end of the connecting member 560 through the connecting link 562 results in horizontal movement of the folding and pressing unit associated with the main supporting standard 62. As the housing 402 of said folding and pressing assembly is secured to the horizontally disposed shaft 510, said shaft 510 moves horizontally in conjunction therewith and limits the movement of said folding and pressing assembly to its horizontal path of travel. The cycle of horizontal movement of the folding and pressing assembly associated with the main supporting standard 62 is controlled by the shape of the cam track 550 on the side of the intermediate drive cam 44.

After the folding operations described above have been completed, the folding and pressing units, together with the folded labels are moved horizontally out of engagement with the contact members 362 and 364 through the action of the above described drive linkage for horizontally reciprocating the folding and pressing units. After the folding and pressing units have moved a sufficient distance in their horizontal reciprocation to have cleared the contact members 362 and 364, the clamping members 346 and 348 having the contact members 362 and 364 mounted thereon are moved upwardly towards their normal non-

clamping position above the line of advance of the label strip. The drive linkage for vertically reciprocating the clamping members 346 and 348 has been described in detail in Section 4 of this specification and particularly the portion thereof beginning at page 46 and continuing through the pages there immediately following.

Fig. 30 illustrates the initial movement of the clamping members 346 and 348 towards their uppermost position in their cycle of operations. At this point the folding and pressing units have been moved horizontally out of engagement with said clamping members. As the folding and pressing units reach the limit of their horizontal movement towards the stacking assembly, with the rollers 428 and 429 traveling within the slots in the slotted lever arms 422 and 423, respectively (see Figs. 17 and 19), the pressure members 398 and 400 are moved upwardly and press the fold in the label against the undercut portions 540 and 542 of the folding arms 514 and 516, respectively. The upward movement of the pressure members 398 and 400 sharply crease or press the fold in the folded label. The drive linkage for the pressure members 398 and 400 has been described above in detail in Section 4 of this specification and particularly the portion thereof starting at page 52. The timing of the upward movement of the pressure members 398 and 400 is controlled by the shape of the cam track on the intermediate drive cam 44. To aid in the formation of a sharp crease along the line of the fold in a folded label, a conventional electrical heating cartridge 564 is mounted on each of the folding arms 514 and 516 and serve to maintain said arms at an elevated temperature whereby an ironing effect is obtained in the formation of the crease of the folded label, during the pressing operation. The pressing operation occurs when the folding and pressing units reach the limits of their horizontal reciprocation towards the stacking assembly.

Fig. 30 also illustrates the position of the folding and pressing units at that point in their horizontal movement when said units have cleared the clamping members 346 and 348. Fig. 31 illustrates the upward travel of the clamping members 346, 348 and shows the fold in the folded label being pressed between pressure members 398 and 400 now positioned in their upward or pressing position against the undercut portions 540 and 542 of the folding arms 514 and 516, respectively. After the pressing of the folded label has been accomplished, the pressure members 398 and 400 are returned to their lower position and the label is freely positioned in the folding and pressing units. When the folded and pressed label is at the pressing location, the label is located between the transfer fingers of the stacking assembly.

(8) Stacking assembly

Also included in the invention is a label stacking assembly adapted to remove the folded and pressed label from the folding and pressing assembly described above in Section 7 of this specification, and to transfer the folded and pressed label to a suitable container for shipment.

The stacking assembly may generally be described as including a folded label transfer unit, each including two sets of transfer fingers, mounted on each of the supporting standards 60 and 62, adapted to receive the folded and pressed label and to rotatably transfer said label into a container for shipment. Each of the folded label transfer units is identical in construction and one

of said units will be described in detail. Associated with each of the transfer units is a drive linkage which effectively operates the transfer unit in the proper cyclic relationship independent of the spacing of the supporting standards.

Figs. 3 and 6 through 10 illustrate various components of the stacking assembly and the drive therefor, as included in the label cutting and folding machine. The details of the stacking assembly are illustrated in Figs. 21, 22, and 23. Referring to the above drawings and particularly to Fig. 23, which illustrates the transfer unit associated with the main supporting standard 60, it being understood that an identical transfer unit is mounted on the supporting standard 62, there is provided a transfer unit mounting member 580 secured to a shaft 582 and positioned adjacent the inner surface of the main supporting standard 60. The shaft 582 is rotatably supported by the main supporting standard 60. Mounted on the transfer unit mounting member 580 and disposed substantially 180° apart are the fixed label transfer fingers 584 and 586. Associated with the fixed transfer finger 584 is a movable transfer finger 588 pivotally mounted on the mounting member 580 at 590 and having an extended arm portion 592 terminating in a roller 594. Associated with the fixed transfer finger 586 is a movable transfer finger 596 pivotally mounted on the mounting member 580 at 598 and having an extended arm portion 600 terminating in a roller 602. The rollers 594 and 602 are adapted to engage the surface of a control disc 604 mounted adjacent the mounting member 580 having recessed portions 606 and 608 positioned on its surface at predetermined locations.

In operation, the transfer units are positioned as shown in Fig. 23, the roller 594 associated with the movable transfer finger 588 being located within the recess 606 on the control disc 604 and thus maintaining the transfer fingers 584 and 588 in a separated or label-receiving position. Similarly, the roller 602 associated with the movable transfer finger 596 is positioned within the recess 608 on the control disc 604 and the fingers 588 and 596 are separated in the label-releasing position.

As described above in the preceding section of this specification, the folding and pressing units are adapted to move horizontally out of engagement with the clamping assembly and towards the stacking assembly. During one portion of the cycle of operations and after the horizontal movement of the folding and pressing members toward the stacking assembly has ceased, the fold in the label is pressed. When the folding and pressing units have reached the limit of their horizontal movement, the folded and pressed label has been introduced between the separated transfer fingers 584 and 588 of the transfer unit illustrated in Fig. 23 and also into the fingers of the corresponding unit mounted on the main supporting standard 62. After the folded label has been introduced between the separated transfer fingers 584 and 588, the control disc 604 is rotated a slight amount through depression of the arm 605 secured thereto.

The arm 605 is connected at its free end to a vertically disposed link 607 positioned adjacent the inner surface of the supporting standard 60. The link is connected to a pin 609 riding in a suitably located slot 610 in the standard 60. Connected to the pin 609 and positioned on the outer surface of the standard 60 is a lever arm 611.

The lever arm 611 is pivoted in the vicinity of its mid-length, as illustrated in Fig. 17 where the lever arm 611a, associated with the standard 62, is illustrated as pivoted at 612 (see Figs. 9 and 10). For the purpose of convenience the remainder of the description of this linkage will refer to the members associated with the standard 62 as these members are most clearly illustrated in the drawings, it being kept clearly in mind that an identical linkage is associated with each of the standards. The other end of the lever arm 611a terminates in a pin 613 which rides in a slotted member 614 forming part of the block 388 included in the clamping assembly (see Figs. 2 and 20).

The upward movement of the slotted member 614 and its corresponding member associated with the standard 60 results in a pivoting of the lever arms 611 and 611a. The pivoting of the lever arm 611 results in a depression of the arm 605 through the action of the link 607. The depression of the arm 605 results in a slight rotative movement of the control disc 604. The initial slight rotative movement of the control disc 604 results in the roller 594 moving out of the recess 606. As the roller 594 moves out of the recess 606 on the control disc 604, the movable transfer finger 588 is pivoted about its pivotal mounting 590 and said movable finger 588 moves toward the fixed finger 584 and clamps the folded and pressed label positioned therebetween. The mounting member 580 is then rotated by a drive linkage which will be described in the portion of the specification immediately following, and said fingers 584 and 588 are maintained in the label clamping position during the period of rotation, or, for as long as the roller 594 is riding on the surface of the control disc 604. The mounting member 580 is rotated through 180° thus moving the fingers 584 and 588 into the position occupied by the fingers 586 and 596 in Fig. 23. Of course, the fingers 586 and 596, as a result of the rotation of the mounting member 580, move into the position previously occupied by the fingers 588 and 584 and are ready to receive a new folded label on the next cycle of horizontal reciprocation of the folding and pressing assembly. When the mounting member 580 has been rotated a sufficient amount so as to cause the roller 594 to engage the recess 608 on the control disc 604, the movable finger 588 will move out of clamping engagement with the fixed finger 584 and the label positioned therebetween may be removed without difficulty. The removal of the label will be described in a later section of this specification describing the packing assembly.

The drive for rotating the mounting member 580 is generally located on the outer surface of the main supporting standard 60 and originates at the vertical connecting members 558 and 560 (see Fig. 17), included in the mechanical drive linkage for horizontally reciprocating the folding and pressing units. Connected to the vertical connecting member 558 is a link 616a corresponding to the link 616 connected to the member 560. The link 616a is connected at its other end to a lever arm 618 (see Figs. 5 and 22) rotatably mounted on the shaft 626 and which serves as a mount for the pawl 620. The pawl 620 drivingly engages a ratchet 622 mounted on and adjacent to a gear 624 rotatably mounted on the shaft 626. The gear 624 engages an idler gear 628 mounted on a shaft 630. The idler gear 628 transmits the driving movement of the gear 624 to a pinion 632 mounted on the shaft 582. Referring to Fig. 17,

it is seen that the connecting member 560 and the corresponding member 558 associated with the standard 60 is arcuately pivoted about the cam follower lever arm supporting shaft 50 through the cam follower lever arm 554 and the horizontally disposed shaft 556. The arcuate motion of the connecting member 558 is transmitted to the lever arm 618 by the connecting member 616a. As the folding and pressing unit is moved away from the clamping member 348 by the action of the connecting member 558, the pawl 620 (see Fig. 22) moves from the position there shown to its adjacent ratchet position, there being no movement of the gear 624. At this time, the transfer unit is in the position illustrated in Fig. 23 with the fingers 584 and 588 being open in their label-receiving position. The label is introduced between the fingers 584 and 588 in the end of the cycle of horizontal movement of the folding and pressing units as described above at an earlier point in this specification. As the folding and pressing units move back towards their position beneath the clamping member 348, the motion of the connecting member 558 is transmitted through the link 616a and causes the pawl 620 to drivingly engage the ratchet 622 and rotate the gear 624 through a predetermined amount. The rotation of the gear 624 rotates the idler gear 628 which in turn rotates the pinion 632 mounted on the shaft 582. Rotation of the pinion 632 mounted on the shaft 582 results in rotation of said shaft 582 and rotation of the mounting member 580 for the transfer unit. The gear ratio between the gears presented in the drive unit is such that when the gear 624 is moved through an angular displacement corresponding to the length of stroke of the connecting member 558, the pinion 632 is rotated through 180°.

To position the transfer unit in the horizontal position illustrated in Fig. 23, the portion of the shaft 582 adjacent the pinion 632 is shaped to be engaged by a plunger 634 maintained in compressive engagement therewith by the spring members 636 mounted on the upper surface of the horizontal supporting platform 144 (see Fig. 7).

The above portion of the specification describes the mechanical drive for the stacking unit mounted on and associated with the main supporting standard 60. It should be clearly kept in mind that a similarly constructed and positioned drive is provided for the transfer unit associated with the main supporting standard 62.

The stacking assembly described above serves to remove the folded label from the folding and pressing assembly when said folding and pressing assembly reaches the limit of its path of horizontal reciprocation, and serves to rotatively transfer said label to a location where it may be removed from the stacking assembly and transferred to a container for shipment by the packing assembly.

As the stacking assembly is composed of a transfer unit, of the type described above, mounted on each of the supporting standards 60 and 62, and each of said units is provided with a drive mounted on or associated with the standards 60 and 62, the stacking assembly operates independently of the spacing of the main supporting standards 60 and 62. As the transfer units move together with the standards 60 and 62 whenever said standards are shifted, the folded and pressed label is always grasped in the vicinity of its ends, which prevents a doubling over or

defective packing of the labels in the container for shipment.

(9) *Packing assembly*

The stacking assembly described above in Section 8 of this specification serves to remove the folded and pressed label from the folding and pressing assembly and to rotatably transfer said label to a suitable container for shipment. In the above portion of the specification, the path of travel of the folded label was described in detail. However, included in the stacking assembly, per se, were no means for removing the folded and pressed label from the label transfer fingers after said label had been transferred to a position in the vicinity of the shipping container. The removal of the folded and pressed label from the transfer fingers of the stacking assembly is accomplished by the packing assembly included as an integral portion of the invention.

The packing assembly may be briefly described as including an adjustable rack adapted to support and position a suitable container and including suitable members which remove the labels from the transfer fingers of the stacking assembly when said transfer fingers are positioned over the container. Associated with the packing assembly are a pair of label packing elements adapted to compressively maintain the labels in the container mounted on the rack in a compact and orderly array.

The packing assembly is formed of two similar packing units, one being mounted upon each of the horizontal reciprocable shafts 510 and 512 which support the folding and pressing units of the folding and pressing assembly. The shafts 510 and 512 are horizontally reciprocated through the drive linkage for horizontally reciprocating the folding and pressing assembly described above in Section 7 of this specification. As the packing assembly is mounted on and supported by the horizontally reciprocable shafts 510 and 512, the packing assembly is adapted to be horizontally reciprocated therewith. The horizontal reciprocating action of the packing assembly is utilized to remove the folded label from the transfer fingers of the stacking assembly and is also used to drive the label packing elements in the proper cyclic relationship.

The presently preferred embodiment of the packing assembly is illustrated in Figs. 3, 4, 5, 6, 7, 9 and 10. The essentials of the packing assembly are illustrated in Figs. 22 and 23. The packing assembly is formed of two packing units, one unit being associated with the main supporting standard 60 and being mounted on the end of the shaft 510 and the other unit being associated with the main supporting standard 62 and being mounted on the end of the shaft 512. For the purpose of simplicity, the packing unit associated with the main supporting standard 60 and mounted on the end of the shaft 510 will be described in detail with the understanding that the unit associated with the main supporting standard 62 and mounted on the end of the shaft 512 is identical in construction and operation.

Mounted on the end of the horizontal reciprocable shaft 512 is a relatively short substantially vertically disposed L-shaped container positioning bracket 650. Slidably mounted on the horizontal reciprocable shaft 510 and spaced from the bracket member 650 by a thumbscrew 652 is an elongated vertically disposed L-shaped container positioning bracket 654. The brackets 650 and 654 are suitably shaped to contain and position

the corners of a conventional cardboard container adapted to receive the folded and pressed labels. The cardboard container is maintained in packing engagement with the elongated member 654 and its corresponding member associated with the main supporting standard 62 by a suitable retaining member, not shown, such as a rubber band or other conventional fastening device. Mounted on the upper portions of the brackets 650 and 654 are suitable plane label depositing guides 656 and 658. The lower portions of the guides 656 and 658 are adapted to extend within the container mounted on the brackets 650 and 654 and serve to position the open mouth of said container as well as to guide the folded and pressed labels into said container.

As the container brackets 650 and 654 are mounted on the horizontal reciprocable shaft 510, said members reciprocate in conjunction therewith and move relative to the main supporting standard 60. It will be remembered that the reciprocable shaft 510 supports the folding and pressing unit associated with the standard 60 and is driven in its horizontal reciprocation by the mechanical drive linkage for said unit described above in Section 7 of this specification. When the folding and pressing unit is positioned beneath the clamping assembly, i. e., during the label strip advancing, clamping and cutting operations, the packing assembly described above is positioned adjacent the end of the main supporting standard 60 as shown in Figs. 3, 4, 5, 6, 22 and 23. It will be noted that the portion of the transfer fingers 586, 596 of the stacking assembly adapted to engage the folded and pressed label is positioned between the brackets 650 and 654 (above the open mouth of a container adapted to receive the folded and pressed labels). As the folding and pressing assembly starts its horizontal reciprocating movement out of engagement with the clamping assembly and towards the rear of the label cutting and folding machine, i. e., towards the stacking assembly, the horizontal reciprocable shaft 510 moves in conjunction therewith in the direction indicated by the arrow A in Fig. 23. The movement of the horizontal reciprocable shaft 510 moves the bracket members 650 and 654 outwardly to the approximate position illustrated in Figs. 7, 9 and 10. As said packing assembly moves outwardly, a label positioned between the transfer fingers 586 and 596 of the stacking assembly is removed from engagement with said stacking assembly by the pushing action of the depositing guide 658 mounted on the bracket 654 and the companion member mounted on the corresponding bracket included in the packing unit associated with the main supporting standard 62.

When the folding and pressing assembly mounted on the horizontal reciprocable shafts 510 and 512 reach the limit of their horizontal movement, and in such position introduce a folded label between the transfer fingers 584 and 588 and between the corresponding fingers of the stacking unit associated with the main supporting standard 62, the packing assembly described above will be moved outwardly beyond the extent of the fingers 586 and 596. Consequently, when the folding and pressing units mounted on the shafts 510 and 512 initiate their return portion of their horizontal reciprocating movement, the concurrent rotation of the transfer units of the stacking assembly is not impeded by the packing unit described above. After the transfer fingers 586 and 596 and the corresponding finger of the

stacking unit associated with the main supporting standard 62 have rotated a sufficient distance to clear the packing unit, the unit returns in the direction of the arrow B to the position shown in Fig. 23. However, the fingers 584 and 588 containing a new folded label and now positioned in depositing engagement with the depositing guides 656 and 658.

To maintain the deposited labels in a tightly packed compressive array within the container for shipment, a label packing member 660 is mounted at one end on a shaft 666 rotatably mounted on the bracket member 650. The shaft 666 is connected at its other end to a link 668. The link 668 is connected at its other end to a connecting rod 662. The other end of the connecting rod 662 is pivotally mounted on the horizontal supporting platform 144 in a mounting lug 664 (see Fig. 7) and therefore does not move in conjunction with the movements of the horizontal reciprocable shaft 510. As said shaft 510 moves outwardly, or in the direction of the arrow labeled A on Fig. 23, the label stack compression member 660 is pivoted together with the shaft 666, through the above described linkage and presses downwardly against the recently deposited label in the container. When the horizontal reciprocable shaft 510 moves in the direction of the arrow labeled B on Fig. 23, the compression member 660 moves out of engagement with the labels in the container mounted between the bracket members 650 and 654 and returns to the position illustrated in Fig. 23.

(10) Miscellaneous

There is also provided a counting mechanism to provide a visual indication both of the total number of labels operated upon by the machine, and of the number of labels cut per order. The counting mechanism includes conventional counters and a linkage for actuating the same and are best shown in Figs. 3, 4, 5, 7 and 9. Mounted upon the upper surface of the horizontal supporting platform 230 is a counter 672 for providing a visual indication of the total number of labels operated upon by the machine. Mounted adjacent the counter 672 is a counter 673 which is utilized to provide an indication of the number of labels cut per order. The counter 673 is provided with a reset thumbscrew 674 to facilitate resetting the counter to zero prior to the start of an order.

The drive for actuating the counters 672 and 673 is a mechanical linkage including the member 675 pivotally secured at one end to the supporting member 334 of the mechanical drive linkage for actuating the label gripping jaw members 238 and 240. The member 675 is connected to an actuating arm 676 mounted on the shaft 677 of the counter 672 and to an actuating arm 679 mounted on the shaft 680 of the counter 673.

The arcuate motion of the supporting member 334 included in the mechanical drive linkage for the label gripping jaw members 238 and 240 occurs once in each complete cycle of machine operation. The arcuate motion of said member 334 is transmitted through the above described linkage to the counters 672 and 673, actuating said counters once for each complete cycle of machine operation.

Also included in the invention is a stop mechanism for stopping the machine with the movable blade member 442 in an open or raised position. The stop mechanism is best illustrated in Figs. 75

1, 2, 5, 6, 7, 8 and 10. There is provided a stop button 686 conveniently located on the horizontal supporting platform 144 (see Figs. 5 and 7). The stop button 686 is electrically connected in series with a cam operated micro-switch 688 (see Figs. 6 and 10). The micro-switch 688 is closed once during each cycle of operation. The stop button 686 and the micro-switch 688 are connected in series with a solenoid 690 (see Figs. 1, 2, 6, 8 and 10). If the stop button 686 is depressed at any point in the cycle of operations and maintained in a depressed condition, the solenoid 690 will be actuated when the cam operated micro-switch 688 is closed. The cam operated micro-switch is actuated at the point in the cycle of operations where the blade member 442 is in an open or raised position. Energization of the solenoid 690 moves the lever arm 692 pivotally mounted on the main drive system supporting member 20. The lever arm 692 operates a declutching mechanism which disengages the multiple channel drive pulley 34 from its shaft 32. The stop mechanism is timed so that the inertia of the machine brings it to a stop with the blade member 442 in an open or raised position.

The above arrangement and structure, from the point of view of both safety requirements and ease of operation, i. e., halting with the blade member 442 raised, permits easy realignment and resetting of the strip of uncut label material.

Having thus described my invention, I claim:

1. In a label cutting and folding machine, in combination, means for intermittently advancing a label strip, a pair of standards for supporting said label strip advancing means, means for varying the spacing between said standards in accordance with the length of label to be cut and folded, and means associated with said label strip advancing means and controlled by the positioning of said standards for automatically varying the length of advance of said label strip advancing means in relation with the spacing of said standards to a total length equal to the spacing of said standards.

2. In a label cutting and folding machine, in combination, means for intermittently advancing a label strip, a pair of supporting members for supporting said label strip advancing means, means for varying the spacing between said supporting members in accordance with the length of label to be cut and folded, means associated with said label strip advancing means and responsive to the spacing of said supporting members for automatically controlling the length of advance over said space between the supporting members of said label strip advancing means in relation with the spacing of said supporting members.

3. In a label cutting and folding machine, in combination, reciprocating means for advancing a label strip, a pair of supporting members for supporting said reciprocating label strip advancing means, means for varying the spacing between said supporting members in accordance with the length of label to be cut and folded, and means associated with said reciprocating means and responsive to the spacing of said supporting members for automatically varying the amplitude of reciprocation of said reciprocating means in relation with the spacing of said supporting members to advance the label strip over the space between said supporting members.

4. In a label cutting and folding machine, in combination, a pair of standards, means for varying the spacing between said standards in ac-

cordance with the length of label to be cut and folded, a reciprocating label strip advancing carriage supported by one of said standards, a second reciprocating label strip advancing carriage disposed in alignment with said first carriage and supported by the other of said standards for advancing a label strip over the spacing between said standards cooperatively with said first carriage, and means associated with said first and second reciprocating carriages and responsive to the spacing of said standards for automatically varying the amplitudes of reciprocation thereof in relation with the spacing of said standards.

5. In a label cutting and folding machine, in combination, a pair of supporting members, means for varying the spacing between said supporting members in accordance with the length of label to be cut and folded, reciprocating means supported by said supporting members for advancing a label strip over the spacing between said members, a fixed drive shaft, mechanical linkages actuated by rotation of said drive shaft for reciprocating said reciprocating means, and means included in said mechanical linkages controlled by the positioning of said supporting members for automatically varying the amplitude of reciprocation of said reciprocating means in relation with the spacing of said supporting members.

6. In a label cutting and folding machine, in combination, a pair of supporting standards, means for varying the spacing between said standards and a fixed location therebetween in accordance with the length of label to be cut and folded, aligned reciprocating means supported by each of said standards for advancing a label strip over said spacing, a fixed drive shaft for said reciprocating means, mechanical linkages actuated by said drive shaft for reciprocating said reciprocating means, and means included in said linkages and responsive to the spacing of said standards for adjustably varying said mechanical linkages so as to control the amplitude of reciprocation of said reciprocating means in accordance with the spacing of said supporting standards.

7. In a label cutting and folding machine, in combination, a pair of substantially parallel supporting standards, means for varying the spacing between said standards in accordance with the length of labels to be cut and folded, a reciprocating carriage supported by one of said standards, a second reciprocating carriage supported by the other of said standards, said first and second reciprocating carriages cooperatively effecting the advance of a label strip across the space between said standards, a fixed drive shaft for each of said first and second reciprocating carriages, mechanical linkages actuated by rotation of said drive shaft for reciprocating said carriages, and means included in said linkages and responsive to the spacing of said supporting standards for adjustably varying said mechanical linkages so as to control the amplitude of reciprocation of said reciprocating carriages in accordance with the spacing of said standards.

8. In a label cutting and folding machine, in combination, a pair of substantially parallel supporting members, a spacer shaft threadedly engaged with said supporting members for varying the spacing between said supporting members in accordance with the length of label to be cut and folded, a reciprocating label strip feeding member supported by each of said supporting members for advancing a label strip from one of said

10 supporting members to the other, a continuously rotating drive shaft, a pair of cam members fixed on said drive shaft, mechanical linkages actuated by rotation of said cams and said drive shaft for reciprocating said label strip feeding members, and automatic means included in said linkages and responsive to the spacing of said supporting members for adjustably varying said mechanical linkages so as to control the amplitude of reciprocation of said label strip feeding members in accordance with the spacing of said supporting members.

15 9. In a label cutting and folding machine, in combination, a pair of supporting members, a spacer shaft threadedly engaged with said supporting members for varying the spacing between said supporting members in accordance with the length of label to be cut and folded, label strip feeding means supported by each of said supporting members for intermittently advancing a label strip from one of said supporting members to the other, a continuously rotating drive shaft, a pair of cam members fixed on said drive shaft, mechanical linkages actuated by rotation of said cams and said drive shaft for operating said label strip feeding means, and automatic means included in said linkages and responsive to the spacing of said supporting members for adjustably varying said mechanical linkages so as to control the length of advance of said label strip feeding means in relation with the spacing of said supporting members.

20 10. A label cutting and folding machine, comprising, in combination, means for advancing a label strip, a pair of standards for supporting said label strip advancing means, means for varying the spacing between said standards in accordance with the length of label to be cut and folded, means associated with said label strip advancing 25 means and responsive to the spacing of said standards for automatically varying the length of advance of said label strip advancing means in relation with the spacing of said standards to advance a label strip over the space between said standards, and means associated with and supported by said standards for cutting, folding, pressing, and stacking labels.

30 11. A label cutting and folding machine, comprising, in combination, reciprocating means for advancing a label strip, a pair of supporting members for supporting said label strip advancing means, means for varying the spacing between said supporting members in accordance with the length of label to be cut and folded, means associated with said label strip advancing 35 means and responsive to the spacing of said supporting members for automatically varying the amplitude of reciprocation of said reciprocating means in relation with the spacing of said supporting members, and means associated with and supported by said supporting members to advance a label strip over the spacing between said members for cutting, folding, pressing, and stacking labels.

35 12. A label cutting and folding machine, comprising, in combination, a pair of supporting members, means for varying the spacing between said supporting members in relation with the length of label to be cut and folded, reciprocating means supported by said supporting members for advancing a label strip over the spacing between said supporting members in relation with the length of said label, a fixed drive shaft, mechanical linkages actuated by rotation of said drive 40 shaft for reciprocating said reciprocating means,

means included in said mechanical linkages controlled by the positioning of said supporting members for automatically varying the amplitudes of reciprocation of said reciprocating means in relation with the spacing of said supporting members, and means associated with and supported by said supporting members for cutting, folding, pressing, and stacking labels.

13. A label cutting and folding machine, comprising, a pair of substantially parallel supporting members, means for varying the spacing between said supporting members in relation with the length of label to be cut and folded, aligned reciprocating means supported by each of said supporting members for advancing a label strip over said spacing, a fixed drive shaft for said reciprocating means, mechanical linkages actuated by said drive shaft for reciprocating said reciprocating means, means included in said linkages and responsive to the spacing of said supporting members for adjustably varying said mechanical linkages so as to control the amplitude of reciprocation of said reciprocating means in relation with the spacing of said supporting members, and means associated with and supported by said supporting members for cutting, folding, pressing, and stacking labels.

14. A label cutting and folding machine, comprising, a pair of substantially parallel supporting members, a spacer shaft threadedly engaged with said supporting members for varying the spacing between said supporting members in accordance with the length of label to be cut and folded, a reciprocating label strip feeding member supported by each of said supporting members for advancing a label strip from one of said supporting members to the other, a continuously rotating drive shaft, a pair of cam members fixed on said drive shaft, mechanical linkages actuated by rotation of said cams and said drive shaft for reciprocating said label strip feeding members, automatic means included in said linkages and responsive to the spacing of said supporting members for adjustably varying said mechanical linkages so as to control the amplitude of reciprocation of said label strip feeding members in accordance with the spacing of said supporting members, and means associated with and supported by said supporting members for cutting, folding, pressing, and stacking labels.

15. A label cutting and folding machine, comprising, a pair of standards defining an operating zone contained therebetween, means for varying the spacing of said standards in accordance with the length of label to be cut and folded, means mounted on said standards for intermittently advancing a label strip across said operating zone, means associated with said label strip advancing means and controlled by the positioning of said standards for automatically varying the length of advance of said label strip advancing means in relation with the spacing of said standards, and means positioned within said operating zone and supported by said standards for cutting, folding, pressing, and stacking labels.

16. A label cutting and folding machine, comprising, a pair of supporting standards defining an operating zone contained therebetween, means for varying the spacing of said standards in relation with the length of label to be cut and folded, reciprocating means mounted on each of said standards for advancing a label strip across said operating zone, means associated with said reciprocating means and responsive to the spacing of said standards for automatically varying the am-

plitude of reciprocation of said reciprocating means in relation with the spacing of said standards, and means positioned within said operating zone and supported by said standards for cutting, folding, pressing, and stacking labels.

17. A label cutting and folding machine, comprising, a pair of substantially parallel supporting standards defining an operating zone contained therebetween, means for varying the spacing between said standards in accordance with the length of label to be cut and folded, reciprocating means mounted on said standards for advancing a label strip across said operating zone, a fixed continuously rotating drive shaft, mechanical linkages actuated by said drive shaft for reciprocating said reciprocating means, automatic means included in said linkages and responsive to the spacing of said standards for adjustably varying said mechanical linkages so as to control the amplitude of reciprocation of said reciprocating means in accordance with the spacing of said standards, and means positioned within said operating zone and supported by said standards for cutting, folding, pressing, and stacking labels.

18. In a label cutting and folding machine, in combination, a pair of supporting standards defining an operating zone contained therebetween, means for varying the spacing between said standards in relation with the length of label to be cut and folded, coacting oppositely reciprocating means supported by said standards for advancing a label strip across said operating zone, and means associated with said reciprocating means and responsive to the spacing of said standards for automatically varying the amplitudes of reciprocation thereof in relation with the spacing of said standards.

19. A label cutting and folding machine, comprising, a pair of supporting standards defining an operating zone contained therebetween, means for varying the spacing between said standards in accordance with the length of label to be cut and folded, coacting oppositely reciprocating means supported by said standards for advancing a label strip across said operating zone, means associated with said reciprocating means and responsive to the spacing of said standards for automatically controlling the amplitudes of reciprocation thereof in accordance with the spacing of said standards, and means positioned within said operating zone and mounted on said standards for cutting, folding, pressing, and stacking labels.

20. A label cutting and folding machine, comprising, in combination, means for intermittently advancing a label strip, a pair of movable standards for supporting said label strip advancing means, means for varying the spacing between said standards in accordance with the length of label to be cut and folded, means associated with said label strip advancing means and responsive to the spacing of said standards for automatically varying the length of advance of said label strip advancing means over the space between the standards in relation with the spacing of said standards, means associated with and supported by said standards for cutting, folding, pressing and stacking labels, a continuously rotating common drive shaft fixed in location with respect to said movable standards, cam members fixedly mounted on said shaft and rotated thereby, mechanical drive linkages connecting said cam members and said cutting, folding, pressing and stacking means and responsive to rotation of said cam members for operating said

51

cutting, folding, pressing and stacking means, and automatic means included in said mechanical linkages and responsive to the spacing of said supporting members for adjustably varying said linkages so as to preserve the drive connection independent of the spacing of said supporting members.

21. A label cutting and folding machine, comprising, in combination, reciprocating means for advancing a label strip, a pair of supporting members for supporting said label strip advancing means, means for varying the spacing between said supporting members in accordance with the length of label to be cut and folded, means associated with said label strip advancing means and responsive to the spacing of said supporting means for automatically varying the amplitude of reciprocation of said reciprocating means in relation with the spacing of said supporting members to advance the label strip over the spacing of said supporting members, means associated with and supported by said supporting members for cutting, folding, pressing, and stacking labels, a continuously rotating drive shaft, cam members mounted on said drive shaft and rotated thereby, mechanical linkages actuated by rotation of said cam members for operating said cutting, folding, pressing and stacking means, and automatic means included in said mechanical linkages and responsive to the spacing of said supporting members for adjustably varying said linkages in accordance with the spacing of said supporting members.

22. A label cutting and folding machine, comprising, a pair of substantially parallel supporting members, a spacer shaft threadedly engaged with said supporting members for varying the spacing between said supporting members in accordance with the length of label to be cut and folded, a reciprocating label strip feeding member supported by each of said supporting members for advancing a label strip from one of said supporting members to the other, a continuously rotating drive shaft, a pair of label feed cam members mounted on said drive shaft, label feed mechanical linkages actuated by rotation of said label feed cam members and said drive shaft for reciprocating said label strip feeding members, automatic means included in said label feed mechanical linkages and responsive to the spacing of said supporting members for adjustably varying said label feed mechanical linkages so as to control the amplitude of reciprocation of said label strip feeding members in accordance with the spacing of said supporting members, label operating means associated with said supporting members and supported thereon for cutting, folding, pressing, and stacking labels, label operating cam members mounted on said continuously rotating drive shaft, label operating mechanical linkages actuated by rotation of said label operating mechanical cam members for operating said cutting, folding, pressing and stacking means, and automatic compensating means included in said label operating mechanical linkages and responsive to the spacing of said supporting members for adjustably varying said label operating mechanical linkages in accordance with the spacing of said supporting members.

23. A label cutting and folding machine, comprising, in combination, a pair of supporting members, means for varying the spacing between said supporting members in accordance with the length of label to be cut and folded, reciprocating

52

means supported by said supporting members for advancing a label strip over the spacing between said supporting members, a continuously rotating drive shaft, label strip advancing mechanical linkages actuated by rotation of said drive shaft for reciprocating said reciprocating means, means included in said label strip advancing mechanical linkages for automatically and adjustably varying said linkages so as to control the amplitudes of reciprocation of said reciprocating means in accordance with the spacing of said supporting members, label operating means associated with and supported by said supporting members for folding, pressing, and stacking labels, a label operating cam member mounted on said shaft intermediate said supporting members, label operating mechanical linkages actuated by rotation of said label operating cam member for operating said folding, pressing, and stacking means, and automatic means included in said label operating mechanical linkages and responsive to the spacing of said supporting members for adjustably varying said label operating mechanical linkages in accordance with the spacing of said supporting members.

24. In a label cutting and folding machine, in combination, a pair of standards, means for varying the spacing between said standards in accordance with the length of label to be cut and folded, means supported by said standards for intermittently advancing a label strip across the space between said standards, means associated with said label strip advancing means and responsive to the spacing of said standards for automatically varying the length of advance of said label strip advancing means in accordance with the spacing of said standards, clamping means supported by said standards for clamping the advanced portions of said label strip, cutting means mounted on one of said standards for severing said advanced portion from the remainder of said label strip, means supported by said standards for folding said advance severed portion of said label strip, means supported by said standards for pressing the folded labels, and means supported by said standards for stacking the folded and pressed labels.

25. In a label cutting and folding machine, in combination, a pair of standards, means for varying the spacing between said standards in accordance with the length of label to be cut and folded, intermittently operable means supported by said standards for advancing a label strip across the space between said standards, means associated with said label strip advancing means and responsive to the spacing of said standards for automatically varying the length of advance of said label strip advancing means in accordance with the spacing of said standards, clamping means supported by said standards for clamping the advanced portions of said label strip, cutting means mounted on one of said standards for severing said advanced portion from the remainder of said label strip, means supported by said standards for folding said advance severed portion of said label strip, means supported by said standards for pressing the folded labels, means supported by said standards for stacking the folded and pressed labels, a continuously rotating drive shaft, a master cam mounted on said drive shaft and rotated thereby, mechanical linkages actuated by rotation of said master cam for operating said clamping, folding, pressing and stacking means, and automatic means included in said mechanical linkages and responsive to the

spacing of said standards for adjustably varying said linkages in accordance with the spacing of said standards.

26. A label cutting and folding machine, comprising, in combination, a pair of supporting standards, means for varying the spacing between said standards in accordance with the length of label to be cut and folded, means supported by said standards for intermittently advancing a label strip from one of said standards to the other, means associated with said label strip advancing means and responsive to the spacing of said standards for automatically varying the length of advance of said label strip advancing means in accordance with the spacing of said standards, a clamping member having a fold-forming edge supported by each of said standards, means for moving said clamping members into engagement with the advanced portion of said label strip, a folding and pressing member supported by each of said standards including, a folding arm and a pressure member, means for moving said pressure members into engagement with the advanced portion of said label strip at a location coincident with the point of contact of said clamping members for clamping said advanced portion of said label strip, cutting means mounted on one of said standards for severing the advanced clamped portion of said label strip, means for moving the clamped severed portion of said label strip into engagement with said folding and pressing members, means for moving said folding arms into folding engagement with said fold-forming edges of said clamping members for folding the end portions of said severed portion of said label strip over said fold-forming edges, means for effecting the disengagement of said folding and pressing members and the folded label from said clamping members, means for moving said pressure members into compressive engagement with said folding arms for pressing the fold in the folded label, and means supported by said standards for stacking the folded and pressed labels.

27. A label cutting and folding machine, comprising, in combination, a pair of substantially parallel supporting standards, means for varying the spacing between said standards in accordance with the length of label to be cut and folded, reciprocating means associated with each of said standards for advancing a label strip from one of said standards to the other, means associated with said reciprocating label strip advancing means and responsive to the spacing of said standards for automatically varying the amplitude of reciprocation of said reciprocating label strip advancing means in accordance with the spacing of said standards, a clamping member having a fold-forming edge associated with each of said standards, means for moving said clamping members into engagement with the advanced portion of said label strip adjacent said standards, a folding and pressing member supported by each of said standards including a folding arm and a pressure member, means for moving said pressure members into engagement with the advanced portion of said label strip at a location substantially coincident with the point of contact of said clamping members for clamping said advanced portion of said label strip, cutting means mounted on one of said standards for severing the advanced clamped portion of said label strip, means for moving the clamped severed portion of said label strip into engagement with said folding and pressing members, means for moving said folding arms into folding engagement with said fold-forming edges of said clamping members for folding the end portions of said severed portion of said label strip over said fold-forming edges, means for moving said folding and pressing members and the folded label out of engagement with said clamping members, means for moving said pressure members into compressive engagement with said folding arms for pressing the fold in the folded label, means for moving said folding and pressing members together with the folded labels into a stacking position, and means supported by said standards for stacking the folded and pressed labels.

with said folding and pressing members, means for moving said folding arms into folding engagement with said fold-forming edges of said clamping members for folding the end portions of said severed portion of said label strip over said fold-forming edges, means for moving said folding and pressing members and the folded label out of engagement with said clamping members, means for moving said pressure members into compressive engagement with said folding arms for pressing the fold in the folded label, and means supported by said standards for stacking the folded and pressed labels.

28. A label cutting and folding machine, comprising, in combination, a pair of substantially parallel supporting standards, a spacer shaft threadedly engaged with said standards for varying the spacing between said standards in accordance with the length of label to be cut and folded, reciprocating means supported by said standards for advancing a label strip transversely from one of said standards to the other, a fixed drive shaft for said reciprocating means, mechanical linkages actuated by rotation of said drive shaft for reciprocating said reciprocating means, means included in said linkages and responsive to the spacing of said supporting standards for automatically varying the amplitude of reciprocation of said reciprocating means in accordance with the spacing of said standards, a clamping member having a fold-forming edge slidably mounted on each of said standards, means for moving said clamping members into engagement with the advanced portion of said label strip adjacent said standards, a folding and pressing member slidably supported by each of said standards including, a folding arm and pressure member; means for moving said pressure members into engagement with the advanced portion of said label strip at a location substantially coincident with the point of contact of said clamping members, said clamping members and said pressure members cooperating to clamp said advanced portion of said label strip intermediate said standards, cutting means mounted on one of said standards for severing the advanced clamped portion of said label strip, means for moving the clamped severed portion of said label strip into operative engagement with said folding and pressing members, means for moving said folding arms into folding engagement with said fold-forming edges of said clamping members for folding the end portions of said severed portion of said label strip over said fold-forming edges, means for moving said folding and pressing members and the folded label out of engagement with said clamping members, means for moving said pressure members into compressive engagement with said folding arms for pressing the fold in the folded label, means for moving said folding and pressing members together with the folded labels into a stacking position, and means supported by said standards for stacking the folded and pressed labels.

29. A label cutting and folding machine, comprising, in combination, a pair of substantially parallel supporting standards, a spacer shaft threadedly engaged with said standards for varying the spacing between said standards in accordance with the length of label to be cut and folded, a pair of reciprocating carriages supported by said standards for cooperatively advancing a label strip transversely across the space between said standards, a continuously ro-

tating drive shaft, mechanical linkages actuated by rotation of said drive shaft for reciprocating said carriages, means included in said linkages and responsive to the spacing of said standards for automatically varying said linkages so as to control the amplitude of reciprocation of said carriages in accordance with the spacing of said standards, a clamping member having a fold-forming edge slidably mounted on each of said standards, means for moving said clamping members into engagement with the advanced portion of said label strip adjacent said standards, a folding and pressing member slidably supported by each of said standards including, a folding arm and a pressure member, means for moving said pressure members into engagement with the advanced portion of said label strip at a location substantially coincident with the point of contact of said clamping members for clamping said advanced portion of said label strip, cutting means mounted on one of said standards for severing the advanced clamped portion of said label strip, means for moving the clamped severed portion of said label strip into operative engagement with said folding and pressing members, means for moving said folding arms into folding engagement with said fold-forming edges of said clamping members for folding the end portions of said severed portion of said label strip over said fold-forming edges, means for moving said folding and pressing members together with said folded label out of engagement with said clamping members, means for moving said pressure members into compressive engagement with said folding arms for pressing the fold in the folded label, means for moving said folding and pressing members together with the folded label into stacking position, and means supported by said standards for stacking the folded and pressed labels.

30. In a label cutting and folding machine, in combination, a pair of substantially parallel supporting members, a spacer shaft threadedly engaged with said supporting members for varying the spacing between said supporting members in accordance with the length of label to be cut and folded, a reciprocating label strip feeding member supported by each of said supporting members for cooperatively advancing a label strip from one of said supporting members to the other, a continuously rotating drive shaft, a pair of strip-advancing cam members fixed on said drive shaft, strip-advancing mechanical linkages actuated by rotation of said cams and said drive shaft for reciprocating said label feeding members, automatic means included in said strip-advancing linkages and responsive to the spacing of said supporting members for adjustably varying said strip-advancing linkages so as to control the amplitude of reciprocation of said label strip feeding members in accordance with the spacing of said supporting members, a clamping member having a fold-forming edge slidably mounted on each of said supporting members, means for moving said clamping members into engagement with the advanced portion of said label strip, a folding and pressing member slidably supported by each of said standards including, a folding arm and a pressure member; means for moving said pressure members into engagement with the advanced portion of said label strip at a location substantially coincident with the point of contact of said clamping members for clamping said advanced portion of said label strip, cutting means mounted on one of said supporting members for severing the advanced clamped portion of said label strip, means for moving the clamped severed portion of said label strip into engagement with said folding and pressing members, means for moving said folding arms into folding engagement with said fold-forming edges of said clamping members for folding the end portions of said severed portion of said label strip over said fold-forming edges, a master cam member fixed on said drive shaft intermediate said supporting members, a first mechanical linkage actuated by rotation of said master cam member for operating said clamping means, a second mechanical linkage actuated by rotation of said master cam member for operating said folding and pressing member, and means included in said first and second mechanical linkages responsive to the spacing of said supporting members for adjustably varying said linkages in accordance with the spacing of said supporting members.

56

said supporting members for severing the advanced clamped portion of said label strip, means for moving the clamped severed portion of said label strip into engagement with said folding and pressing members, means for moving said folding arms into folding engagement with said fold-forming edges of said clamping members for folding the end portions of said severed portion of said label strip over said fold-forming edges, driving means for said clamping members and said folding and pressing members positioned intermediate said standards, and linkage means actuated by said driving means for sequentially operating said clamping members and said folding and pressing members independent of the spacing between said supporting members.

31. In a label cutting and folding machine, in combination, a pair of substantially parallel supporting members, a spacer shaft threadedly engaged with said supporting members for varying the spacing between said supporting members in accordance with the length of label to be cut and folded, a reciprocating label strip feeding member supported by each of said supporting members for advancing a label strip from one of said supporting members to the other, a continuously rotating drive shaft, a pair of strip-advancing cam members fixed on said drive shaft, strip-advancing mechanical linkages actuated by rotation of said strip-advancing cams and said drive shaft for reciprocating said label feeding members, automatic means included in said strip-advancing linkages and responsive to the spacing of said supporting members for adjustably varying said strip-advancing linkages so as to control the amplitude of reciprocation of said label strip feeding members in accordance with the spacing of said supporting members, a clamping member having a fold-forming edge slidably mounted on each of said supporting members, means for moving said clamping members into engagement with the advanced portion of said label strip, a folding and pressing member slidably supported by each of said standards including, a folding arm and a pressure member; means for moving said pressure members into engagement with the advanced portion of said label strip at a location substantially coincident with the point of contact of said clamping members for clamping said advanced portion of said label strip, cutting means mounted on one of said supporting members for severing the advanced clamped portion of said label strip, means for moving the clamped severed portion of said label strip into engagement with said folding and pressing members, means for moving said folding arms into folding engagement with said fold-forming edges of said clamping members for folding the end portions of said severed portion of said label strip over said fold-forming edges, a master cam member fixed on said drive shaft intermediate said supporting members, a first mechanical linkage actuated by rotation of said master cam member for operating said clamping means, a second mechanical linkage actuated by rotation of said master cam member for operating said folding and pressing member, and means included in said first and second mechanical linkages responsive to the spacing of said supporting members for adjustably varying said linkages in accordance with the spacing of said supporting members.

32. A label cutting and folding machine, comprising, in combination, a pair of substantially

parallel supporting standards, a spacer shaft threadedly engaged with said standards for varying the spacing between said standards in accordance with the length of label to be cut and folded, reciprocating means supported by said standards for advancing a label strip transversely from one of said standards to the other, a continuously rotating drive shaft, a first and second mechanical linkage each actuated by rotation of said drive shaft for reciprocating said reciprocating means, means included in said first and second linkages and responsive to the spacing of said supporting standards for automatically adjustably varying said linkage so as to control the amplitude of reciprocation of said reciprocating means in accordance with the spacing of said standards, a clamping member having a fold-forming edge slidably mounted on each of said standards, means for moving said clamping members into engagement with the advanced portion of said label strip adjacent said standards, a folding and pressing member slidably supported by each of said standards including, a folding arm and pressure member; means for moving said pressure members into engagement with the advanced portion of said label strip at a location substantially coincident with the point of contact of said clamping members, said clamping members and said pressure members cooperating to clamp said advanced portion of said label strip intermediate said standards, a cutting knife mounted on one of said standards for severing the advanced clamped portion of said label strip, means for moving the clamped severed portion of said label strip into operative engagement with said pressing and folding members, means for moving said folding arms into folding engagement with said fold-forming edges of said clamping members for folding the end portions of said severed portion of said label strip over said fold-forming edges, means for moving said folding and pressing members and the folded label out of engagement with said clamping members, means for moving said pressure members into compressive engagement with said folding arms for pressing the fold in the folded label, means for moving said folding and pressing members together with the folded labels into a stacking location, stacking means supported by said standards for removing the folded and pressed labels from said stacking location and transferring said labels to a container, a cam member mounted on said drive shaft intermediate said supporting standards, a third mechanical linkage actuated by said cam member for operating said clamping members, a fourth mechanical linkage actuated by said cam member for operating said folding and pressing members, a fifth mechanical linkage actuated by said cam member for operating said stacking means, and automatic means included in said third, fourth and fifth mechanical linkages and responsive to the spacing of said supporting members for adjustably varying said third, fourth and fifth mechanical linkages in accordance with the spacing of said supporting members.

33. A label cutting and folding machine, comprising, in combination, a pair of substantially parallel supporting standards, a spacer shaft threadedly engaged with said standards for varying the spacing between said standards in accordance with the length of label to be cut and folded, a pair of reciprocating carriages supported by said standards for cooperatively advancing a label strip transversely across the space between said standards, a continuously rotating

drive shaft, a pair of cam members fixed on said drive shaft, first and second mechanical linkages actuated by rotation of said drive shaft and said cam members for reciprocating said carriages, 5 means included in said linkages and responsive to the spacing of said standards for automatically varying said linkages so as to control the amplitude of reciprocation of said carriages in accordance with the spacing of said standards, 10 a clamping member having a fold-forming edge supported by each of said standards, means for moving said clamping members into engagement with the advanced portion of said label strip adjacent said standards, a folding and pressing member supported by each of said standards including a folding arm and a pressure member, 15 means for moving said pressure members into engagement with the advanced portion of said label strip at a location substantially coincident with the point of contact of said clamping members for clamping said advanced portion of said label strip, cutting means mounted on one of said standards for severing the advanced clamped portion of said label strip, means for moving the clamped severed portion of said label strip into operative engagement with said folding and pressing members, means for moving said folding arms into folding engagement with said fold-forming edges of said clamping members for folding the end portion of said advanced portion of said label strip over said fold-forming edges, means for moving said folding and pressing members together with said folded label out of engagement with said clamping members, means 20 for moving said pressure members into compressive engagement with said folding arms for pressing the fold in the folded label, means for moving said folding and pressing members together with the folded label into a stacking location, 25 stacking means supported by said standards for removing the folded and pressed labels from said stacking location and transferring said labels to a container, a master cam member mounted on said drive shaft intermediate said supporting standards, a third mechanical linkage actuated by said cam member for operating said clamping members, a fourth mechanical linkage actuated by said cam member for operating said folding and pressing members, a fifth mechanical linkage actuated by said cam member for operating said stacking means, and means included in said third, fourth and fifth mechanical linkages and responsive to the spacing of said supporting members for adjustably varying said third, fourth and fifth mechanical linkages in accordance with the spacing of said supporting members, said last mentioned automatic means providing for operation of said clamping, folding, pressing and stacking means independent of the spacing of said standards.

34. A label cutting and folding machine, comprising, a pair of substantially parallel supporting standards defining a label operating zone contained therebetween, a spacer shaft threadedly engaged with said supporting standards for varying the spacing of said standards in accordance with the length of label to be cut and folded, reciprocating means mounted on each of said standards for cooperatively advancing a label strip across the space between said standards, a continuously rotating drive shaft, first and second cam members fixedly mounted on said shaft externally of said operating zone, first and second mechanical linkages actuated by said first and second cam members for reciprocating said

reciprocating label strip advancing means, automatic means included in said first and second mechanical linkages and responsive to the spacing of said supporting members for adjustably varying said first and second mechanical linkages so as to control the amplitude of reciprocation of said reciprocating label strip advancing means in accordance with the spacing of said supporting members, clamping members mounted on and supported by said supporting members for clamping the advanced portion of said label strip contained within said operating zone, a knife mounted on and supported by one of said supporting members for severing the advanced clamped portion of said label strip positioned within said operating zone, a folding and pressing assembly mounted on and supported by each of said supporting members for folding and pressing the ends of the severed portion of said label strip positioned within said operating zone, and a stacking member mounted on and supported by each of said supporting members for removing the folded and pressed labels from said folding and pressing assembly within said operating zone.

35. A label cutting and folding machine, comprising, a pair of substantially parallel supporting standards defining a label operating zone contained therebetween, a spacer shaft threadedly engaged with said supporting standards for varying the spacing of said standards in accordance with the length of label to be cut and folded, reciprocating means mounted on each of said standards for cooperatively advancing a label strip across the space between said standards, a continuously rotating drive shaft, first and second cam members fixedly mounted on said shaft externally of said operating zone, first and second mechanical linkages actuated by said first and second cam members for reciprocating said reciprocating label strip advancing means, automatic means included in said first and second mechanical linkages and responsive to the spacing of said supporting members for adjustably varying said first and second mechanical linkages so as to control the amplitude of reciprocation of said reciprocating label strip advancing means in accordance with the spacing of said supporting members, clamping members mounted on and supported by said supporting members for clamping the advanced portion of said label strip contained within said operating zone, a knife mounted on and supported by one of said supporting members for severing the advanced clamped portion of said label strip positioned within said operating zone, a folding and pressing assembly mounted on and supported by each of said supporting members for folding and pressing the ends of the severed portion of said label strip positioned within said operating zone, a stacking member mounted on and supported by each of said supporting members for removing the folded and pressed labels from said folding and pressing assembly within said operating zone, a master cam mounted on said drive shaft intermediate said supporting members within said operating zone, a third mechanical linkage actuated by said master cam for transmitting motive power to said clamping members, a fourth mechanical linkage actuated by said master cam for transmitting motive power to said folding and pressing assembly, a fifth mechanical linkage actuated by said master cam for transmitting motive power to said stacking members, and means included in said third, fourth, and fifth

mechanical linkages for automatically varying said linkages in accordance with the spacing of said supporting members.

36. A label cutting and folding machine, comprising, a pair of standards defining an operating zone contained therebetween, means for varying the spacing between said standards in accordance with the length of label to be cut and folded, means mounted on said standards for intermittently advancing a label strip across an operating zone, means associated with said label strip advancing means and responsive to the spacing of said standards for automatically varying the length of advance of said label strip advancing means in accordance with the spacing of said standards, clamping members mounted on and supported by said supporting members for clamping the advanced portion of said label strip contained within said operating zone, a knife mounted on and supported by one of said supporting members for severing the advanced clamped portion of said label strip positioned within said operating zone, a folding and pressing assembly mounted on and supported by each of said supporting members for folding and pressing the ends of the severed portion of said label strip positioned within said operating zone, and a stacking member mounted on and supported by each of said supporting members for removing the folded and pressed labels from the folding and pressing vicinity within said operating zone.

37. A label cutting and folding machine, comprising, a pair of standards defining an operating zone contained therebetween, means for varying the spacing between said standards in accordance with the length of label to be cut and folded, means mounted on said standards for intermittently advancing a label strip across the operating zone, means associated with said label strip advancing means and responsive to the spacing of said standards for automatically varying the length of advance of said label strip advancing means in accordance with the spacing of said standards, clamping members mounted on and supported by said supporting standards for clamping the advanced portion of said label strip contained within said operating zone, a knife mounted on and supported by one of said supporting standards for severing the advanced clamped portion of said label strip positioned within said operating zone, a folding and pressing assembly mounted on and supported by each of said supporting standards for folding and pressing the ends of the severed portion of said label strip positioned within said operating zone, a stacking member mounted on and supported by each of said supporting standards for removing the folded and pressed labels from the folding and pressing vicinity within said operating zone, a continuously rotating drive shaft, a master cam mounted on said drive shaft intermediate said supporting standards, mechanical linkages actuated by said master cam for operating said clamping members, said folding and pressing assemblies, and said stacking members, and automatic means included in said mechanical linkages for automatically varying said linkages in accordance with the spacing of said supporting standards.

38. In a label cutting and folding machine, in combination, a pair of substantially parallel supporting standards, a shaft threadedly engaged with each of said standards for varying the spacing of said standards in accordance with

the length of label to be cut and folded, a reciprocating carriage supported by one of said standards for advancing the end of a label strip to the center of the space between said standards, a second reciprocating carriage supported by the other of said standards for advancing the end of said label strip across the remaining space between said standards, a drive shaft fixed in location with respect to said standards, a cam fixedly mounted on said drive shaft for each of said reciprocating carriages, a mechanical linkage actuated by each of said cams for reciprocating said reciprocating carriages, and means included in each of said mechanical linkages for automatically varying the amplitude of reciprocation of said reciprocating carriages in accordance with the spacing of said standards.

39. The combination as set forth in claim 38, wherein the means included in each of said mechanical linkages for automatically varying the amplitude of reciprocation of said reciprocating carriages in accordance with the spacing of said standards comprises, a pivotal member fixed in location with respect to said drive shaft and having a slot along its length, said pivotal member being arcuately displaceable in response to rotation of said cam member, and a connecting rod vertically reciprocable in response to the arcuate displacement of said pivotal member, said connecting rod being positioned within said slot in accordance with the location of said standard.

40. In a label cutting and folding machine, in combination, a pair of substantially parallel supporting standards, means for moving one of said standards for varying the spacing between said standards, means supported by one of said standards for intermittently advancing a label strip across the space between said standards, and means for driving said label strip advancing means including means responsive to the spacing of said standards for automatically varying the length of advance of said label strip advancing means in accordance with the spacing of said standards.

41. In a label cutting and folding machine, in combination, a pair of standards, means for moving one of said standards for varying the spacing between said standards in accordance with the length of label to be cut and folded, a reciprocating label strip advancing carriage mounted on said movable standard for advancing a label strip over the spacing between said standards, and a driving linkage for reciprocating said carriage including means responsive to the spacing of said standards for automatically varying the amplitude of reciprocation of said carriage in accordance with the spacing of said standards.

42. In a label cutting and folding machine, in combination, a pair of supporting members, means for moving one of said supporting members for varying the space between said supporting members in accordance with the length of label to be cut and folded, a reciprocating label strip advancing carriage mounted on said movable supporting member for advancing a label strip over the spacing between said supporting members, a driving linkage for reciprocating said carriage, and automatic means included in said linkage and responsive to the spacing of said supporting members for adjustably varying said driving linkage so as to control the amplitude of reciprocation of said reciprocating carriage in accordance with the spacing of said supporting members.

43. In a label cutting and folding machine, in combination, a pair of supporting members, means for moving one of said supporting members for varying the space between said supporting members in accordance with the length of label to be cut and folded, a reciprocating label strip advancing carriage mounted on the movable supporting member for effecting the advance of a label strip across the space between said supporting members, a drive shaft fixed in location with respect to said movable supporting standard, a mechanical linkage actuated by rotation of said drive shaft for reciprocating said carriage, and means included in said linkage and responsive to the spacing of said supporting members for adjustably varying said mechanical linkage so as to control the amplitude of reciprocation of said carriage in accordance with the spacing of said supporting members.

20 44. A label cutting and folding machine, comprising, in combination, a pair of supporting members, means for moving one of said supporting members for varying the space between said supporting members in accordance with the length of label to be cut and folded, a reciprocating label strip advancing carriage mounted on the movable supporting member for effecting the advance of a label strip across the space between said supporting members, a drive shaft fixed in location with respect to said supporting members, a mechanical linkage actuated by rotation of said drive shaft for reciprocating said carriage, means included in said linkage and responsive to the spacing of said supporting members for adjustably varying said linkage so as to control the amplitude of reciprocation of said carriage in accordance with the spacing of said supporting members, and means mounted on said supporting members for cutting, folding, pressing and stacking labels.

45. The combination as set forth in claim 44 including mechanical linkage driving means for said cutting, folding, pressing and stacking means, said last mentioned mechanical linkage driving means including means responsive to the spacing of said supporting standards for adjustably varying said mechanical linkage driving means in accordance with the spacing of said supporting members.

50 46. In a label cutting and folding machine, in combination, a pair of substantially parallel movable supporting members defining a label operating zone contained therebetween, means for varying the spacing between said supporting members in accordance with the length of label to be cut and folded, means for disposing a label strip across said operating zone, a clamping member having a clamping arm perpendicularly disposed therewith slidably mounted on each of said supporting members, a cam member mounted on a rotatable drive shaft and fixedly positioned intermediate said movable supporting members, a mechanical drive linkage connecting said cam member with said clamping members and responsive to rotation of said cam member for moving said clamping arms into engagement with the portion of the label strip disposed across said operating zone, a coacting pressure member associated with each of said clamping arms and supported by said supporting members, a second mechanical drive linkage connecting said cam member with said pressure members and responsive to rotation of said cam member for moving said pressure members into engagement with the portion of said label strip at a location

substantially coincident with the point of contact of said clamping members for clamping said advanced portion of said label strip, and means included in both of said linkages responsive to the spacing of said supporting members for adjustably varying said linkages so as to preserve the drive connection and proper cyclical actuation of said clamping members and pressure members independent of the spacing of said supporting members from each other and from said fixedly mounted cam member.

47. In a label cutting and folding machine, in combination, a pair of substantially parallel supporting members, means for varying the spacing between said supporting members in accordance with the length of label to be cut and folded, means for disposing a label strip across the space between said supporting members, a fixed blade member mounted on one of said supporting standards, a movable blade member pivotally connected to said fixed blade member, said blade members cooperatively adapted to sever the advanced portion of the label strip disposed intermediate said supporting members, a rotatable drive shaft fixedly positioned with respect to said supporting members, a drive cam fixedly mounted on said rotatable drive shaft with respect to said supporting members, a mechanical drive linkage connecting said cam with said blade member and responsive to rotation of said cam member for cyclically actuating said movable blade member, and means included in said mechanical linkage for adjustably varying said linkage in accordance with the spacing of said supporting standards so as to preserve the drive connection and proper cyclical actuation of said movable blade member independent of the spacing of said supporting members from each other and from said fixedly mounted drive cam.

48. In a label cutting and folding machine, in combination, a pair of supporting members, means for varying the spacing between said supporting members in accordance with the length of label to be cut and folded, means for advancing a label strip over the spacing of said supporting members, a fixed blade member mounted on one of said supporting standards, a movable blade member pivotally connected to said fixed blade member, said blade members coacting to sever the advanced portion of said label strip disposed between said supporting members, a drive member fixedly located with respect to said movable supporting members, a mechanical drive linkage connecting said drive member with said movable blade member and responsive to rotation of said fixed drive member for cyclically actuating said movable blade member, and means included in said mechanical linkage for adjustably varying said linkage in accordance with the spacing of said supporting members so as to preserve the drive connection and proper cyclical actuation of said movable blade member independent of the spacing of said supporting members from each other and from said fixedly located drive member.

49. In a label cutting and folding machine, in combination, a pair of movable supporting members, means for varying the spacing between said supporting members in accordance with the length of label to be cut and folded, a folding and pressing member slidably supported by each of said supporting members, each of said folding and pressing members including a folding arm and a pressure member, a rotatable drive member fixedly positioned intermediate said support-

ing members, mechanical drive linkages connecting said drive member with said folding arms and said pressure members responsive to rotation of said drive member for cyclically actuating said folding arms and said pressure members and for moving the same longitudinally of said supporting members, and means included in said mechanical linkages responsive to the spacing of said supporting members for adjustably varying said linkages so as to preserve the drive connection and proper cyclical actuation of said folding arms and said pressure members independent of the spacing of said supporting members from each other and from said fixedly positioned drive member.

50. In a label cutting and folding machine, in combination, a pair of substantially parallel supporting members, means for varying the spacing between said supporting members in accordance with the length of label to be cut and folded, a folding and pressing unit slidably supported by each of said supporting members, a rotatable drive shaft fixedly positioned with respect to said supporting members, a drive cam fixedly mounted on said drive shaft intermediate said supporting members, mechanical drive linkages connecting said drive cam with said folding and pressing unit responsive to rotation of said drive cam for cyclically actuating said folding and pressing units and for moving the same longitudinally of said supporting members, and means included in said mechanical linkages and responsive to the spacing of said supporting standards for adjustably varying said linkages so as to preserve the drive connection and proper cyclical actuation of said folding and pressing unit independent of the spacing of said supporting members from each other and from said fixedly mounted drive cam.

51. In a label cutting and folding machine, in combination, a pair of supporting members defining an operating zone contained therebetween, means for introducing a label into said operating zone, means for varying the spacing between said supporting members in accordance with the length of label to be cut and folded, a rotating stacking unit mounted on each of said supporting members for removing a finished label from said operating zone, a drive member fixedly positioned in relation to said supporting members, drive linkage means connecting said drive member with said stacking units and responsive to movement of said drive member actuating said stacking units, and means included in said linkage means for adjustably varying the same so as to preserve the drive connection and proper cyclical operation of said stacking units independent of the spacing of said supporting members from each other and from said fixedly positioned drive member.

52. In a label cutting and folding machine, in combination, a pair of substantially parallel supporting members defining a label operating zone contained therebetween, means for varying the spacing between said supporting members in accordance with the length of label to be cut and folded, means for introducing a label strip into said operating zone, a stacking unit rotatably mounted on each of said supporting members for removing a finished label from said operating zone, each of said stacking units including, a pair of label transfer fingers spaced 180 degrees apart, means to cyclically open and close said transfer fingers, a drive cam mounted on a drive shaft and fixedly positioned intermediate said sup-

porting members, a mechanical drive linkage connecting said drive cam with said stacking units and responsive to rotation of said drive cam for cyclically rotating said stacking units, and means included in said mechanical linkage responsive to the spacing of said supporting members for adjustably varying said linkage so as to preserve the drive connection and operation of said stacking units in the proper cyclic relationship independent of the spacing of said supporting members from each other and from said fixedly positioned drive cam.

53. In a label cutting and folding machine of the type described, in combination, a pair of supporting members, means for varying the spacing between said supporting members in accordance with the length of label to be cut and folded, a reciprocating carriage mounted on one of said supporting members for advancing a label strip across the space between said supporting members; a drive member, means drivingly connecting said drive member and said carriage for cyclically reciprocating said carriage, a cutting assembly for severing the advanced portion of said label strip, means drivingly connecting said drive member and said cutting assembly for cyclically actuating said cutting assembly independent of the spacing of said supporting members, and an assembly for trimming the leading edge of said label strip prior to its advance across the space between said supporting members, including, auxiliary drive means connecting said drive member with said last mentioned assembly for independently advancing said reciprocating carriage through a distance determined by the amount of label to be trimmed independent of the spacing of said supporting members, said auxiliary drive means including means for preserving the drive connection and proper cyclical actuation of said assembly independent of the spacing of said supporting members, and means included in said means connecting said cutting assembly and said drive member for preserving said drive connection and actuation of said assembly for

severing the portion to be trimmed from the remainder of said label strip independent of the positioning of said supporting members.

54. In a label cutting and folding machine of the type described, in combination, a pair of supporting members, means for varying the spacing between said supporting members in accordance with the length of label to be cut and folded, a reciprocating carriage mounted on one of said supporting members for advancing a label strip across the space between said standards, a drive for cyclically reciprocating said carriage through a distance determined by the spacing of said supporting members, a cutting assembly for severing the advanced portion of said label strip, a drive for cyclically actuating said cutting assembly independent of the spacing of said supporting members, and an assembly for trimming the leading edge of said label strip prior to its advance across the space between said supporting members, comprising, a drive cam fixedly positioned with respect to said supporting members, an auxiliary mechanical drive linkage responsive to rotation of said drive cam for independently advancing said reciprocating carriage through a distance determined by the amount of label to be trimmed, means included in said auxiliary linkage for adjustably varying said linkage in response to the spacing of said supporting members so as to maintain any predetermined independent advance of said carriage independent of the spacing of said supporting members, and means included in said drive for said cutting assembly for cyclically actuating said assembly so as to sever the portion of said label strip to be trimmed from the remainder of said label strip.
